UNITED STATES PATENT OFFICE.

RODNEY G. RICHARDSON, OF CHICAGO, AND MARTIN L. NELSON, OF PARK RIDGE, ILLINOIS, ASSIGNORS, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed March 29, 1922, Serial No. 547,866. Renewed December 24, 1928.

The present invention relates in general to automatic telephone systems, but more especially to multi-office automatic telephone systems; and the object of the invention is to produce a new and improved "director", or registering, translating, and sending apparatus, for controlling the automatic switches, and new and improved grouping or trunking arrangements for such directors.

In our prior application Serial No. 538,551, filed February 23, 1922, an apparatus of the above character is illustrated and described. The director shown in that application is common to a large number of subscribers and is adapted to be connected to a first selector trunk when such trunk is taken for use by a calling subscriber, whereupon registering devices in the director respond to the impulses from the subscriber's calling device and record the various characters, letters or digits, constituting the called telephone number. As soon as the first three characters, or letters, are registered, a sending device is set in motion and transmits series of impulses in accordance with a code derived by a translation from these letters. The code impulses operate a series of selector switches to trunk the call to the desired office, and the sending device then transmits the registered digits in the called telephone number to the selected office without translation to operate other selectors and a connector to complete the connection to the called line. Means is provided whereby the transmission of any series of impulses except the first is made contingent upon the completion of the trunk hunting movement in the selector which responds to the preceding series of impulses.

The director forming the subject-matter of the present invention resembles the one above referred to, and operates according to the same general principles, but is simpler and is less expensive to manufacture. There are a number of new features among which may be pointed out the following:

According to the principal feature of improvement, the directors are divided into groups, and "director selectors" are inserted between the first selector trunks and the directors. This arrangement reduces the number of different calls handled by each director to approximately one-tenth of the total number, whereas in the former system each director had to be capable of handling all

calls. The construction of the improved director is, therefore, much less complicated and its cost is correspondingly reduced. One saying in particular which may be mentioned is brought about by the use of only one two-motion Strowger switch per director, instead of the nine which were formerly required. Various modifications of the general grouping plan are possible, as will be pointed out.

A second feature is the elimination of the revertive control of the sending switch by means of which the starting of the sending switch to operate any selector was made contingent on the completion of the trunk hunting movement of the preceding selector. Instead of the revertive control, a standard time interval of approximately one-third of a second is inserted between successive series of impulses, this time interval being slightly longer than the maximum hunting time of a Strowger selector switch.

A third feature is a simple and inexpensive director for calling long distance. A group of these directors is accessible from the 0 level of the director selectors.

Other features relate mainly to circuit improvements and will be pointed out in detail hereinafter.

Referring to the drawings, Figures 1 to 6, inclusive, are circuit diagrams of sufficient of the apparatus used in a complete director system to illustrate the preferred form of the invention, Fig. 1 being a circuit diagram of a first selector trunk and a director selector, Figs. 2 to 5, inclusive, being circuit diagrams of a complete director for use in handling regular traffic, while Fig. 6 is a circuit diagram of a long distance director.

Figure 7 is a circuit diagram of a modified form of first selector trunk equipment which may be substituted for Fig. 1.

Figure 8 is a trunking diagram of the system which is shown in detail in Figs. 1 to 6, inclusive.

Figures 9, 10, and 11 are diagrams of modified trunking or grouping arrangements which are desirable in some cases.

Figure 12 is a front view of the subscriber's calling device showing the numbering of the dial.

Figure 13 is a layout showing how sheets 1 to 6, inclusive, should be joined together.

It will be advisable first to consider the grouping and trunking layout, Fig. 8, as an

understanding of this will assist in the explanation of the rest of the drawings. The trunking diagram, Fig. 8, is intended principally to show the grouping of the directors, 5 although a number of switch trains are illustrated also which will be of assistance in explaining the operation of the directors. It may be stated at the outset that the illustration of the trunking is only fragmentary. 10 Each office in the system is provided with first, second, and third selectors for handling the interoffice trunking, and in any given office the trunk lines extending to the other offices are in general taken from the banks of 15 the third selectors, although a certain number of offices may be reached directly from the second selector banks. Assuming that in a particular case a group of interoffice trunk lines is taken from a third selector level, 20 these trunk lines would extend by way of repeaters to incoming fourth selectors at the terminating office, and connections would be completed at that office by means of the incoming fourth selectors, fifth selectors and 25 connectors. An arrangement similar to this is shown diagrammatically in Fig. 8. The subscriber at substation A in the West office may set up a connection with the subscriber at substation A¹ in the Torrington office by 30 means of the primary and secondary line switches C¹ and C², and a director in group No. 4, which director is adapted to register the called number TORrington 2345 and operate the first, second, and third selectors E¹, E², 35 and E³ in the originating office, and the fourth selector E⁴, the fifth selector E⁵, and the connector H in the terminating office to complete the connection.

A connection from the subscriber at station 40 A to the subscriber at station A² in the Lothair office may be established in the same manner with the exception that since the Lothair office is a tandem office, an additional selector will be employed. A director in the 45 fourth group is used, and the connection is established by means of selectors E¹, E², and E³ in the originating office, and selectors E⁴⁴, E⁵⁵, and E⁶, and connector H¹ in the terminating office. It may be stated that the 50 incoming fourth selector E⁴⁴ has access to a group of trunks extending to local fifth selectors on one level and on the other nine levels has access to groups of trunks extending to other offices. For instance, the fourth 55 level may contain terminals of trunks which extend by way of repeaters such as repeater R³ to another office.

The trunking of calls to the various special operators indicated will be sufficiently obvious from the foregoing, and at any rate will be described fully in the course of the detailed explanation of the system.

An explanation of the grouping of the directors necessarily entails a brief discussion 60 of the directory numbering system. The ex-

change names are retained, as in manual systems, and each subscriber's telephone number, that is, the number which has to be dialled, consists of the first three letters of his exchange name and four digits. In the directory 70 the first three letters of the exchange names are printed in capitals and preferably also in heavy type in order to distinguish these three letters from the others and thus avoid confusion on the part of the subscribers. 75 The calling device dials are, of course, marked with letters in addition to the usual digits, as indicated in Fig. 12.

It may be perceived now from an inspection 80 of Fig. 12, that all the offices or exchanges of the system fall into nine natural groups in accordance with the finger holes in which the initial letters of the exchange names appear. There would, of course, be ten groups, but for the fact that the digit 0 85 is used for long distance, which makes it impossible to have any exchange names beginning with the letter O. To explain the grouping of exchanges a little more in detail, all the exchanges the names of which begin with 90 letters I or P constitute the first group, while all those exchanges the names of which begin with A, J, or R constitute a second group. Similarly, the other seven groups are composed of those exchanges whose initial letters occur in finger holes 3 to 9, inclusive. 95 When the initial letter of any exchange name in the first group is dialled one impulse will be transmitted, when the initial letter of any exchange name in the second group is dialled 100 two impulses will be transmitted, and so on.

From the above facts it will be obvious that the dialling of the first digit might conceivably be utilized to select the group of exchanges which includes the exchange in which 105 the desired subscriber is located, but it cannot do this directly in the sense of actually trunking the call to a switching point for the group, because the trunking is all done in accordance with a code which is not definitely 110 determined on until the third letter is dialled. The same result may be accomplished indirectly however by providing as many groups of directors as there are group of offices and by using the first digit to select a group of directors. This is accomplished in the preferred 115 form of the invention by equipping each first selector trunk with a director selector, which has access to all of the groups of directors.

In Fig. 8 a first selector trunk is shown 120 extending from the bank of the secondary rotary line switch C² to the first selector E¹. A relay equipment, indicated by the reference character D, is included in the trunk, which is normally open at this point. From the relay equipment D the incoming and outgoing sections of the trunk extend to the director selector F. When a calling subscriber who has seized the trunk line dials the first letter 125 of the called number, the selector F is oper- 130

ated over the incoming section of the trunk and raises its wipers opposite the level which corresponds to the letter dialled, thus selecting a particular group of directors. The selector then rotates automatically to hunt an idle director in the selected group, and when the selecting movement ceases, the incoming and outgoing sections of the trunk are extended to the selected director to provide for the registration of the remaining letters and digits, and to provide for the transmission of the required series of impulses by the director to operate the regular train of switches by means of which the connection is completed.

Theoretically, there should be ten groups of directors, nine groups for handling the regular traffic, and one group for handling long distance calls; but in practice it will often be found that the full number of groups is not necessary. There are two cases in which the number of groups can be reduced, both of which are illustrated in Fig. 8. The first case is where there is no conflict between the exchange names in two different groups of exchanges, which makes it possible to use one group of directors for handling traffic to both groups of exchanges. For instance, it may happen that in a certain system the second and third letters in the names of all the exchanges in the first group form different two-letter combinations than do the second and third letters in the exchange name of any exchange in the fourth group. When this is true, the first letters in the exchange names are not needed to distinguish the exchanges from each other, and all the exchanges of the first and fourth groups may be combined into one group served by a single group of directors. This arrangement is illustrated in Fig. 8, in which the first group of directors is omitted, the first level of the director selector F being multiplied with the fourth level. The No. 4 group of directors handles the traffic to the exchanges in the first group as well as the traffic to the exchanges in the fourth group.

The second case is where certain groups are entirely missing, that is, when there are certain groups of letters which do not occur as the initial letters in any exchange names. In the present case it will be assumed that there are no exchanges the names of which begin with letters G, X, H, or Y. Letters G and X correspond to the eighth level, while letters H and Y correspond to the ninth level, and accordingly these two levels are multiplied together and give access to a small group of special directors, similar to the long distance directors, which trunk calls accidentally arriving at the eighth and ninth levels to an operator.

The grouping illustrated will now be readily understood. There are six groups of regular directors, numbered from 2 to 7 in the

drawing, and accessible from levels 1 to 7, inclusive, which are provided for handling traffic to exchanges in groups 1 to 7, inclusive; and two groups of special directors, one of which is accessible from the tenth level and is used for handling long distance calls, while the other group is accessible from the eighth and ninth levels and is used for handling calls accidentally arriving at the dead levels of the director selectors.

The number of directors in each group will, of course, vary in accordance with the traffic which the directors are required to handle, which in turn depends on the number and size of the offices in the groups. In some cases it may be that not more than ten directors are required in a group. In a case of this kind the trunking from the director selectors to the directors is exceedingly simple, for as is well known a selector switch of the Strowger type has access to ten trunk lines on each level and each director selector may have direct access to all of the directors. For instance, if the traffic to the offices in group No. 3 is such as to require only ten directors to handle it, there would be only ten directors in the No. 3 group and the trunk lines extending to these directors would be multiplied in the third level of all the director selectors such as the director selector F. Another group of exchanges may include so many exchanges that the traffic requires fifteen directors to handle it. Assuming that the No. 2 group of exchanges is of this size, there would be fifteen directors in the No. 2 group, which would require a slightly different trunking arrangement. A convenient method of procedure would be to divide the director selectors such as the selector F into two groups, so far as the second levels thereof is concerned, and terminate the trunk lines from directors 1 to 10 in the second level of the first group, while directors 6 to 15 would be terminated in the second level of the second group. This would make five directors of the second group individual to each group of director selectors, and five common to both groups. An elaboration of this idea will serve in the case of still larger groups of directors. For instance, it may be that there are fifty directors in the fourth group. The director selectors would then be divided into nine groups with respect to their fourth levels, and the first group may be given access to directors 1 to 10, the second group to directors 6 to 15, the third group to directors 11 to 20, etc. Where such large groups are involved it may be desirable, in order to increase the efficiency, to combine them all into one group by means of secondary line switches in accordance with the well-known practice.

In order to avoid possible confusion, the explanation of the various modified grouping arrangements of the directors such as are shown in Figs. 9, 10, and 11 will be deferred.

until after the system embodying the preferred arrangement has been fully described.

The apparatus in Figs. 1 to 6, inclusive, may now be explained more in detail. Fig. 1 shows the detailed circuit arrangements of the first selector trunk which is depicted in Fig. 8 together with the associated director selector. The trunk conductors 10, 11, and 12 extend from multiple sets of contacts in the banks of secondary rotary line switches such as the line switch C², one of which sets of contacts is indicated by reference characters 22, 23, and 24, by way of the relay equipment D to the first selector E¹. The relay equipment D comprises a single relay, and the line conductors of the trunk are normally open at contacts of this relay, both the incoming and outgoing sections of the trunk being extended to the director selector F which is located directly below the trunk relay equipment D. The first selector E¹ and the director selector F are vertical and rotary switches of the Strowger type, and each has access to 100 sets of contacts arranged in ten horizontal rows or levels. The circuit of the first selector E¹ is a standard two-wire circuit such as is in common use, and the circuit of the director selector F is very much the same, although it has been modified somewhat in order to take care of the somewhat different functions which the director selector has to perform.

One of the directors for handling regular traffic is shown complete in Figs. 2 to 5, inclusive, and comprises the master digit controller M, Fig. 2; the B and C impulse register J, Fig. 4; a thousand's register M¹, a hundred's register M², a ten's register M³, and a unit's register M⁴, all of which are shown in Fig. 2; an impulse sending switch S, Fig. 3; a sequence switch S¹, Fig. 5; and an intermediate distributing frame I. D. F., Fig. 4.

The master digit controller M and the four digit registers M¹ to M⁴, inclusive, are simple ten-point step by step switches, each of which is provided with an operating magnet and a release magnet, and a set of off normal springs which are operated when the switch 50 wipers are advanced out of their normal position.

The B and C impulse register J is a Strowger switch of the vertical and rotary type having 100 sets of contacts arranged in ten horizontal rows or levels. The operating and release magnets of the switch J are controlled over conductors coming from the master digit controller M, Fig. 2, and consequently, the switch requires no relays. Four wipers are provided, indicated by reference characters 55 306 to 309, inclusive, and shown to the right of the operating magnets in Fig. 4, which also shows the first five sets of contacts in the tenth level of the bank to which these 60 wipers have access. All of the contact sets in

the bank which correspond to working exchanges, or which correspond to exchanges which it is anticipated will be installed, are wired to terminal sets on the left-hand side of the I. D. F., as is shown in the case of the second, fourth, and fifth contact sets; while all those contact sets which do not correspond to working exchanges, are multiplied together and are connected to a single set of terminals on the left-hand side of the I. D. F., as is shown in the case of the first and third contact sets. Of course, if desired, all of the contact sets could be connected to the left-hand side of the I. D. F. in regular rotation without regard to whether they are actually 70 in use or not, but the strapping of the dead contact sets mentioned above is recommended as a method of decreasing the size of the intermediate distributing frame. 75

The right-hand side of the intermediate distributing frame consists of fifteen or more bus-bars, each having a plurality of terminals in order to provide facilities for cross-connecting any terminal on the left-hand side of the I. D. F. with any bus-bar. The first nine 80 bus-bars correspond to the nine digits, 1 to 9, inclusive, and are so marked in the drawing. These bus-bars are connected in multiple with the banks of the register switches M¹ to M⁴, inclusive, and with the bank of the sending switch S, as is shown in Figs. 2 and 3. Bus-bars X, Y, and Z provide for automatically advancing the sequence switch S¹ on office codes which have less than the maximum 85 number of series of impulses; bus-bars S^{w1} and S^{w2} are special switching bus-bars which are used to control the switching through 90 at the trunk equipment D when calling the operator's or similar numbers; while the bus-bar RL is associated with a special relay 95 which is used to trunk calls to an operator over a route which requires a greater number 100 of series of code impulses than is provided for in ordinary cases. 105

The intermediate distributing frame represented diagrammatically in Fig. 4 is assumed to be of a standard type, with standard terminal arrangements on one side and a series of bus-bars on the other side, and having permanent cable connections between 110 the left-hand side and the bank of the B and C impulse register J, and permanent cable connections from the bus-bars on the right-hand side to the banks of the register and sending switches. If desired, however, 115 this standard type of construction can be deviated from to a considerable advantage, at least so far as the initial cost is concerned. One method of procedure which has been favorably considered, is to mount the bus-bars as a unit directly in the rear of the bank of the B and C register switch, which 120 will permit jumpers to be run directly from the bank of the switch to the bus-bars. This 125 arrangement permits the terminals on the 130

left-hand side of the frame to be entirely omitted and will effect a considerable saving.

The sending switch S, Fig. 3, and the sequence switch S¹, Fig. 5, are step by step rotary switches of the type in which the wipers move in a forward direction only. In further explanation of these switches it should be stated that they are of the type in which the wipers are advanced when the 10 stepping magnet retracts its armature rather than when the stepping magnet is energized.

The general object and scope of the invention having been pointed out, the operation of the apparatus involved will now be described more in detail, and for this purpose it will be assumed first that the subscriber at station A, Fig. 8, desires to establish a connection with the subscriber at station A¹, whose telephone number is TORrington 2345. 20 When the receiver is removed at station A, the calling line is extended in a known manner to a trunk line such as the one extending to the first selector E¹ by means of the primary line switch C¹ and a secondary line switch such as the secondary line switch C². Assuming that the secondary line switch in use connects with the set of bank contacts indicated by reference characters 22, 23, and 24, Fig. 1, the two conductors of the calling line will be connected with trunk conductors 10 and 12, and a circuit will be completed over the said trunk conductors and conductors 60 and 61 for the double wound line relay 64 of the director selector F. Relay 64 is 30 accordingly energized at armature 72 and closes a circuit for the slow-acting release relay 65. On energizing, the latter relay connects ground to conductor 76 at armature 74, and at armature 75 connects ground to the release trunk conductor 11. The latter operation completes a holding circuit for the operated line switches in the usual and well understood manner.

The calling subscriber will now operate his calling device dial in accordance with the first letter T of the called number, as a result of which four interruptions will be produced in the circuit of his line, and the line relay 64 of the director selector F will be deenergized four times. At each deenergization the line relay 64 transmits an impulse of current to the vertical magnet 69 over a path which extends from the grounded conductor 76 by way of the resting contact of armature 73 and the said armature, armature 83 and its resting contact, winding of the slow-acting series relay 66, and the winding of the vertical magnet 69 to battery. By the operation of the vertical magnet responsive to these impulses, the wipers 85 to 88, inclusive, are raised step by step and are brought to rest opposite the fourth level of bank contacts. Relay 66 is energized in series with the vertical magnet 69 and since it is slow-acting, it holds its armature attracted during the ver-

tical movement of the switch. On the first vertical step the off normal springs are shifted and a circuit is completed from the grounded conductor 63 by way of the working contact of armature 77, off normal springs 78, and the winding of the stepping relay to battery. Upon energizing, relay 67 establishes a locking circuit for itself at armature 79 and at armature 80 prepares a circuit for the rotary magnet 70. An instant after the vertical movement of the switch is completed, the slow-acting relay 66 falls back and completes the circuit of the rotary magnet 70, which energizes and advances the wipers 85 to 88, inclusive, into engagement with the first set of contacts in the level opposite which they were raised. Near the end of its stroke the armature of the rotary magnet 70 opens its interrupter contact and breaks the locking circuit of the stepping relay 67, and the stepping relay then falls back and breaks the circuit of the rotary magnet, which accordingly falls back also and again closes its interrupter contact. If the first set of contacts is busy, there will be a ground potential on the test contact engaged by the test wiper 87, switching relay 68 will remain short circuited, and the stepping relay 67 will be reenergized to again close the circuit of the rotary magnet 70. 90 The rotary magnet will thus be operated a second time and the switch wipers will be advanced into engagement with the second set of contacts in the fourth level. This operation, it may be stated is repeated as long as 100 the test wiper 87 continues to encounter grounded test contacts. When an idle test contact is reached, which we will assume to be the test contact 91 of the trunk line extending to the director equipment shown in 105 Figs. 2 to 5, inclusive, the test wiper 87 will find no ground potential, the stepping relay 67 will not be energized again, and the rotation of the switch will cease. The switching relay 68, being now no longer short circuited, 110 is energized over a circuit extending from the grounded conductor 76 by way of the winding of the said relay 68, the interrupter contact of the rotary magnet, the off normal springs 78, and the winding of the stepping relay 67. The latter relay, it may be mentioned, is not operated at this time because of the relatively high resistance of the switching relay 68. 115 When the switching relay 68 pulls up at 120 the end of the selecting movement of the director selector F, a considerable number of circuit changes are brought about. At armature 84, of relay 68 the grounded conductor 76 is connected direct to the test wiper 87, and a ground potential is thus placed upon the test contact 91 and its multiples in the banks of other director selectors in order to 125 make the selected director busy. A ground potential is also placed on the holding con- 130

ductor 102, and since this conductor is connected by way of normally closed contacts at armatures 125 and 127, Fig. 3, to the local holding conductor 203, relays 110 and 111, Fig. 3, and relay 210, Fig. 2, will be energized. Relay 111, on energizing, removes ground from the upper bank of the sequence switch S^1 at armatures 133, and at armature 132 disconnects wiper 113 of the sending switch S from the stepping magnet 115. Relay 110, on energizing, disconnects relay 109 at armatures 129 and 131, and at armature 130 removes ground from the release conductor 204. Relay 210 of the master digit controller M, on attracting its armature 209, connects the common conductor 299 coming from the timer T to the winding of relay 205, and at armature 217 prepares a circuit for relay 206.

Another result of the energization of switching relay 68 in the director selector F, is the shifting of the local operating circuit from the vertical magnet to wiper 88 at armature 83, which results in the preparation of an impulsing or control circuit for the vertical magnet 303 of the B and C impulse register J, Fig. 4, which may be traced as follows: from the grounded conductor 73 by way of the resting contact of armature 73 and said armature (since the line relay 64 is now energized the circuit is now open at this point), armature 83 and its working contact, wiper 88, bank contact 92, conductor 103, armature 138 and its resting contact, conductor 202, the winding of the low resistance slow-acting series relay 207, wiper 218 of the master digit controller M in first position, conductor 301, and the winding of the vertical magnet 303 to battery. The preparation of this circuit places the B and C impulse register J in condition to receive the next two series of impulses from the calling line.

As a further result of the energization of the switching relay 68, the conductors 25 and 26 which are normally connected with the trunk conductors 20 and 22, are extended at armatures 81 and 82 to the wipers 85 and 86, respectively, and are thus connected by way of bank contacts 89 and 90 with conductors 100 and 101. This operation completes a bridge across the trunk conductors 20 and 22 which may be traced from the trunk conductor 20 by way of normally closed contacts controlled by armature 14, conductor 25, working contact of armature 81 and said armature, wiper 85, bank contact 89, conductor 100, resting contact of armature 123 and the said armature, armature 137 and its resting contact, conductor 101, bank contact 90, wiper 86, armature 82 and its working contact, and normally closed contact springs controlled by armature 18 to the trunk conductor 22. Upon the closure of the circuit above traced, the line relay 30 of the selector E^1 is energized and establishes a circuit for the slow-acting release relay 31. On energizing, the latter relay grounds the release trunk conductor 11 at the upper armature, and at its lower armature prepares a circuit for the vertical 70 magnet 35.

When the calling subscriber operates his calling device for the next letter in the called number, or the letter O, ten interruptions will be produced in his line circuit and the line 75 relay 64 in the director selector F will be de-energized ten times. Accordingly, the line relay 64 will transmit a series of ten impulses over the previously traced operating circuit to the vertical magnet 303 of the B and C impulse register J. In response to these impulses the magnet 303 operates to raise the wipers 306 to 309, inclusive, step by step until they stand opposite the tenth level of bank contacts.

The slow-acting relay 207 in the master digit controller M is energized in series with the vertical magnet 303 of switch J and retains its armature 215 in operated position throughout the series of impulses. At the working contact of armature 215 a circuit is completed for relay 208 which is thus maintained energized also. At the end of the series of impulses relay 207 falls back and breaks the circuit of relay 208, whereupon the latter relay deenergizes also. Since relay 208 is slow acting, however, it will not de-energize until an instant after relay 207 has retracted its armature and a momentary impulse of current will be transmitted to the stepping magnet 212 of the master digit controller M from ground by way of armature 215 and its resting contact, armature 216 and its working contact, and the winding of the stepping magnet 212 to battery. By the operation of the stepping magnet 212, wipers 218 and 219 are advanced into second position. It will be noticed that when relay 207 energizes, it disconnects ground from the lower terminal of relay 206 and causes relay 110 110 to fall back in case it has been previously energized by timer T, and relay 205. Relays 205 and 206 are provided in order to switch the call and free the director in case the calling subscriber should fail to complete his 115 number, and in the ordinary operation of the system these relays have no function.

When the calling subscriber dials the next letter in the called number, or the letter R, two interruptions will be produced in his line 120 circuit and the line relay 64 of the director selector will be deenergized twice. This relay accordingly transmits two impulses of current over the previously traced operating circuit, and now since the wiper 218 of the master digit controller M is standing in second position, these current impulses will pass over conductor 302 and through the rotary magnet 304. By the resulting operation of the rotary magnet wipers 306 to 309, inclusive, 125 130

are advanced two steps in a rotary direction and are brought to rest in engagement with the second set of contacts in the tenth level.

During the rotary movement of the B and C impulse register J, the slow-acting series relay 207 of the master digit controller is energized the same as it was during the vertical movement, and completes a circuit for the slow-acting relay 208. At the end of the 5 rotary movement these two relays deenergize an instant apart and thus cooperate in transmitting an impulse of current to the stepping magnet 212 of the master digit controller M, the wipers of which accordingly advance to 10 the third position. At wiper 218 the operating or control circuit coming from the director selector F over conductor 202 is shifted from the rotary magnet of the B and C impulse register J to the stepping magnet 227 of the 15 thousand's register M¹, while at wiper 219 a ground is placed on starting conductor 400.

Responsive to the grounding of the start wire 400, the sending switch S begins to transmit impulses in accordance with the office 20 code which has been determined on by the dialling of the first three letters of the called number, but it is thought best to defer the explanation of these operations in order to permit an explanation of the operation of the register switches M¹ to M⁴, inclusive, in registering the four digits of the called number. When the calling subscriber operates his calling device in accordance with the digit 2 of the called number, the line relay 64 of the director selector F responds in the usual manner and transmits two impulses to the stepping magnet 227 of the thousand's register M¹. By the operation of the stepping magnet 227 wiper 244 is advanced two steps into engagement with the second contact in its associated bank. When the switch leaves its normal position the off normal springs are shifted and spring 236 by engaging its working contact prepares a circuit for grounding conductor 421 which is completed when the slow-acting series relay 231 deenergizes at the end of the series of impulses. Relay 231, it may be stated, is energized in series with the stepping magnet 227 and holds its armature 235 attracted during the stepping movement of the register switch in order to prevent the conductor 421 from being grounded until the registration of the digit is completed.

The slow-acting series relay 207 is also energized in series with the stepping magnet 227 and in conjunction with relay 208 operates to transmit another impulse of current to the stepping magnet 212 of the master digit controller at the proper time, whereby wipers 55 218 and 219 are advanced to the fourth position. Wiper 218 in shifting from third to fourth position, shifts the control circuit from the stepping magnet 227 of register switch M¹ to the stepping magnet 226 of 60 hundred's register switch M². No circuit

changes are brought about by the further movement of wiper 219, since contacts 3 to 10, inclusive, in the bank associated with this wiper are multiplied together. It may be 70 stated that wiper 219 should preferably be so constructed that when advanced from contact to contact it will engage a new contact each time before it disengages the preceding one.

It will be unnecessary to describe in minute detail how the other three register switches 75 M², M³, and M⁴ are operated responsive to the dialling of the remaining three digits of the number. It will be sufficient to point out briefly that when the hundred's digit 3 is dialled, the line relay 64 will transmit three 80 impulses of current through relays 207 and 230 and through the stepping magnet 226 in series, whereby the said stepping magnet is operated to advance wiper 245 into engagement with the third contact in its bank. At 85 the end of the stepping movement relay 230 which holds up its armature 234 during the operation of the register switch, deenergizes and connects ground to conductor 422. At the same time the slow-acting relays 207 and 90 208 transmit an impulse to the stepping magnet 212 of the master digit controller in order to advance the wipers 218 and 219 to fifth position. In a manner similar to the above, when the calling subscriber dials the ten's digit 4 95 and the unit's digit 5, a series of four impulses is first transmitted to the stepping magnet 225 of the ten's register M³, and a series of five impulses is then transmitted to the stepping magnet 224 of the unit's register M⁴, it 100 being understood, of course, that the control circuit is shifted from magnet 225 to magnet 224 at the proper time by wiper 218 of the master digit controller M. Wiper 246 of register switch M³ is accordingly advanced 105 into engagement with the fourth contact in its bank, while wiper 247 of the register switch M⁴ is advanced into engagement with the fifth contact in its bank. Conductors 423 and 424 are grounded when the slow-acting 110 relays 229 and 228 fall back after the completion of the operation of their respective associated register switches.

The operation of the sending switch S, Fig. 3, may now be taken up. As stated before, this switch begins operating to transmit impulses in accordance with the required office code as soon as the last of the three letters of the number have been dialled, the actual starting of the sending switch being accomplished by the grounding of the starting wire 400 when the wiper 219 of the master digit controller M arrives in third position. The code in accordance with which the call is trunked to the Torrington office is 654, as may be perceived from an inspection of the trunking diagram, Fig. 8, and accordingly, the second set of contacts in the tenth level of switch J, which set of contacts is selected by the dialling of the letters TOR, is so cross- 120 125 130

connected at the intermediate distributing frame as to cause the transmission of three series of impulses, the first series comprising six interruptions, the second series comprising five interruptions, and the third series comprising four interruptions. More in detail, terminal 341 is cross-connected to bus-bar No. 6, terminal 340 is cross-connected to bus-bar No. 5, terminal 339 is cross-connected to bus-bar No. 4, and terminal 338 is cross-connected to bus-bar X. These cross-connections will cause the required series of impulses to be transmitted by the sending switch S, as will be understood shortly.

Conductor 400 extends to the sequence switch S¹, Fig. 5, where it is connected to wiper 404 and to the first four contacts in the bank of wiper 405. Accordingly, when this conductor is grounded, a ground is placed on the No. 6 contact in the bank of the stop wiper 114 of the sending switch S, the circuit being traceable from the grounded conductor 400 by way of sequence switch wiper 404 in first or normal position, conductor 411, wiper 306 of register switch J and the contact now engaged thereby, terminal 341 on the left-hand side of the I. D. F., a jumper connecting this terminal with bus-bar No. 6, and thence by way of conductor 366 to the No. 6 contact in the bank of stop wiper 114 of the sending switch. At the same time that the above circuit is completed, a circuit is completed for the impulsing relay 107 of the sending switch over the following path: from the grounded conductor 400 by way of wiper 405 in first position, conductor 425, resting contact of armature 119 and the said armature, resting contact of armature 140 and the said armature, winding of the impulsing relay 107, and through the interrupter I to battery. The interrupter I is continuously driven, and consists of any suitable cam arrangement for intermittently connecting battery to the relays such as relay 107 at the rate of about ten times per second. When this circuit is closed, therefore, or shortly afterwards, depending on the position of the interrupter I, relay 107 is energized and opens the impulsing contact at armature 123, this operation being of no effect, however, due to the fact that the contact at armature 123 is short circuited at armature 120 of relay 106. Relay 107 also closes the circuit of stepping magnet 115 at armature 124, and the said magnet is energized. When the circuit of relay 107 is broken by the interrupter I an instant later, the relay falls back, again closes its interrupter contact, and breaks the circuit of the stepping magnet 115, which thereupon retracts its armature and advances the wipers 113 and 114 one step. A circuit is now completed for relay 106 by wiper 113, and this relay, upon energizing, removes the short circuit from the impulsing contact 123 at armature 120, prepares a locking circuit

for stop relay 105 at armature 121, and at armature 122 connects ground to conductor 426, this completing a circuit for the stepping magnet 402 of the sequence switch S¹. Magnet 402 is accordingly energized, but without affecting the position of its wipers, which like the wipers of the sending switch are advanced when the magnet retracts its armature. The second time that the circuit of relay 107 is closed by interrupter I, the said relay closes the circuit of the stepping magnet 115 as before and also, since relay 106 is now energized, it opens the circuit of the line relay 30 of the selector E¹ at impulsing contact 123. When the circuit of relay 107 is broken by the interrupter, it deenergizes and breaks the circuit of the stepping magnet 115, which retracts its armature and advances wipers 113 and 114 one more step, thus bringing the stop wiper 114 into engagement with the No. 1 contact in its bank. It will be seen that the sending switch S is caused to make an initial or false step before it actually begins transmitting impulses, and this, it may be stated, is done in order to insure that the first impulse transmitted will be of the standard length.

The energizations and deenergizations of relay 107 continue in quick succession under control of the interrupter I. After the second deenergization, which terminates the first impulse or interruption of the control circuit, the stop wiper 114 is advanced into engagement with its No. 1 contact, as stated, after the third deenergization wiper 114 is advanced into engagement with its No. 2 contact, and so on, until finally, after the seventh deenergization, and after the sixth interruption has been produced in the control circuit, the stop wiper is advanced into engagement with the No. 6 contact. Since the first digit in the interoffice code is 6, the required number of impulses have now been transmitted to the selector E¹. As previously explained, the No. 6 contact in the lower bank of the sending switch is grounded at this time, and when the stop wiper 114 comes into engagement with this contact, a circuit is completed for the stop relay 105. Upon energizing, the stop relay closes a locking circuit for itself at armature 117, at armature 119 opens the circuit of the impulsing relay 107 in order to prevent the transmission of any more impulses, and at armature 116 completes an automatic rotary circuit for the stepping magnet 115 by connecting wiper 113 with the said magnet through its interrupter contact. On the closure of this automatic rotary circuit the stepping magnet 115 operates as a buzzer and advances the wipers 113 and 114 one step. A circuit is now completed for relay 106 by wiper 113, and this relay, upon energizing, removes the short circuit from the impulsing contact 123 at armature 120, prepares a locking circuit

As a further result of the energization of the stop relay 105, the circuit of the stepping magnet 402 of the sequence switch S¹ is broken at armature 118, and the said magnet is

deenergized, thus advancing the sequence switch wipers to second position. As a result of the movement of sequence switch wiper 404 from first to second position, ground is removed from the No. 6 contact in the bank of the stop wiper 114 and is connected to the No. 5 contact, the new circuit being traceable from the grounded starting conductor 400 by way of wiper 404 in second position, conductor 412, wiper 307 of register switch J and the contact engaged by said wiper, terminal 340, a jumper connecting this terminal with bus-bar No. 5, and conductor 365 to the No. 5 contact in the bank of the stop wiper. The movement of the other sequence switch wipers is without particular effect at this time.

The operation of the first selector E¹, Fig. 1, in response to the first series of code impulses may now be briefly explained. As described in the foregoing, the circuit of the line relay 30 of selector E¹ is interrupted six times at the impulsing contact 123 in the sending switch S and the said line relay is accordingly deenergized six times. Six impulses are thus transmitted to the vertical magnet 35 which operates to raise the wipers 50, 51, and 52 step by step until they arrive at the sixth level of bank contacts. The slow-acting series relay 32 is energized in series with the vertical magnet 35 and at the first upper movement of the switch shaft completes a circuit for the stepping relay 33, which latter relay establishes a locking circuit for itself and also prepares a circuit for the rotary magnet 37. At the end of the vertical movement of the switch, relay 32 falls back and closes the rotary magnet circuit to initiate the automatic trunk hunting operation. The wipers of the switch are now advanced step by step by rotary magnet 37 under control of the test wiper 51 and the stepping relay 33. When an idle trunk is reached, which we will assume is the one indicated in the drawing, the test wiper 51 fails to find a ground on the test contact 54, and the rotary movement of the switch is arrested. Switching relay 34 is now energized in the usual manner, places a ground on the test wiper 51 in order to make the selected trunk busy, and extends the trunk conductors 20 and 22 by way of armatures 40 and 43, wipers 50 and 52, and bank contacts 53 and 55 to the trunk conductors 56 and 58. Trunk conductors 56, 57, and 58, it may be stated, extend to and terminate in the second selector E², the circuits of which are not shown in detail, but which is shown diagrammatically in Fig. 8. On the extension of the trunk to the second selector E² the line and release relays of this selector are energized in the usual manner, the switch is prepared for its vertical operation, and a ground is placed upon the release trunk conductor 57.

Returning now to the sending switch S, when the switch reaches its normal position

after the transmission of the first series of code impulses, wiper 113 will engage an ungrounded contact and the circuit of relay 106 will be broken. On deenergizing, relay 106 again closes the shunt around the impulsing contact 123 at armature 120, and at armature 121 breaks the locking circuit of the stop relay 105. The latter relay, on deenergizing, again closes the circuit of the impulsing relay 107 at armature 119 and the transmission of the second series of code impulses is started. As indicated in the drawing, relays 105 and 106 are made slow-acting in order to introduce a brief time interval between the transmission of successive series of impulses, thus giving the selector switches time for their automatic trunk hunting operations. The second series of code impulses is now transmitted similar to the manner in which the first series was transmitted. When the circuit of the impulsing relay 107 is completed at armature 119 by the deenergization of the stop relay 105, the said impulsing relay begins to operate intermittently under the control of the interrupter I, and advances the sending switch step by step through the medium of the stepping magnet 115. At the first step of the switch relay 106 is energized, removes the shunt from the impulsing contact 123 at armature 120, prepares a locking circuit for the stop relay at armature 121, and closes the circuit of the sequence switch magnet 403 at armature 122. On the second energization of the impulsing relay 107 and on the succeeding energizations thereof, impulses will be transmitted over the switch control circuit comprising conductors 100 and 101 in the manner described in the foregoing, and by the time the stop wiper 114 arrives at the No. 5 contact in its bank a series of five impulses will have been transmitted. The No. 5 contact in the bank of the stop wiper 114 is now grounded and accordingly, the stop relay 105 is again energized, a locking circuit being established at armature 117 as before. Relay 105 also breaks the circuit of impulsing relay 107 at armature 119, closes the automatic rotary circuit at armature 116, and at armature 118 breaks the circuit of the sequence switch magnet 402. On deenergizing, the sequence switch magnet advances the wipers to third position, whereupon ground is removed from the No. 5 contact in the bank of the stop wiper 114 and is connected to the No. 4 contact. The circuit extends from the grounded conductor 400 by way of wiper 404 in third position, conductor 413, wiper 308 of the register switch J and the contact engaged thereby, terminal 339, a jumper connecting this terminal with bus-bar No. 4, and conductor 364 to the No. 4 contact in the bank of the stop wiper.

On the return of the sending switch S to normal after the transmission of the second series of code impulses, relays 106 and 105 are successively deenergized and the circuit of

the impulsing relay 107 is again completed at armature 119. It will be unnecessary to go over the operation of the sending switch again in detail in view of the preceding explanation, as it will be readily understood that the sending switch will now proceed to transmit a series of four impulses, relay 106 being energized on the first step and stop relay 105 being energized as soon as the stop wiper 114 arrives at the No. 4 contact in its bank. The energization of the stop relay stops the transmission of impulses at the proper point, closes the automatic rotary circuit for advancing the sending switch to normal position, and breaks the circuit of the sequence switch magnet 402, which was closed by the energization of relay 106. On deenergizing, magnet 402 advances the sequence switch wipers from third to fourth position. Since there are only three series of impulses in the office code, the sequence switch S^1 must now be advanced automatically through its fourth position in order to prepare the circuits for the transmission of the thousand's digit as soon as the sending switch S has restored to normal. This is accomplished automatically, due to the fact that terminal 338 is cross-connected to the bus-bar X at the I. D. F., instead of to any of the bus-bars which are associated with the bank of the sending switch. When the sequence switch wiper 404 arrives in fourth position, a circuit is completed for the stepping magnet 402 which extends from the grounded conductor 400 by way of wiper 404 in fourth position, conductor 414, wiper 309 of register switch J and the contact engaged thereby, terminal 338, a jumper connecting this terminal with bus-bar X , conductor 370, wiper 403 in fourth position, and through the interrupter contact and the winding of the stepping magnet 402 to battery. Upon the closure of the foregoing circuit, the stepping magnet 402 is energized momentarily and the sequence switch wipers are advanced to fifth or thousand's position.

The three series of code impulses have now all been transmitted and the director is in readiness to start the transmission of the impulses which correspond to the registered digits. In order that the progress of the call may be kept in mind, it may be stated that in response to the second series of impulses, the wipers of the selector E^2 , Fig. 8, are raised to the fifth level, whereupon a trunk line is selected which extends to a third selector which we will assume is the selector E^3 . In response to the third series of code impulses, the wipers of the selector E^3 are raised to the fourth level, and an idle trunk extending to the Torrington office is selected, the trunk taken for use being assumed to be the one which extends by way of the repeater R to the selector E^4 . The repeater R is of a standard type and includes means such as a repeating

coil by means of which the trunk is divided into two inductively connected sections. It includes also a line relay operated over the incoming section to repeat impulses into the outgoing section, and a slow-acting release relay for grounding the extended release trunk conductor 57.

When the sequence switch S^1 is automatically advanced to the fifth or thousand's position, wiper 404 places ground on the wiper 244 of the thousand's register M^1 , and wiper 405 leaves the multiplied contacts which are connected with the grounded conductor 400 and engages its No. 5 contact to which is connected conductor 421 coming from the thousand's register switch. As a result of the latter circuit change, when the sending switch S returns to normal after having transmitted the last series of code impulses, the transmission of the series of impulses which corresponds to the thousand's digit of the number is not started unless this digit has been registered, for unless the register switch M^1 has completed its operation there will be no ground on conductor 421. Under ordinary circumstances, however, the calling subscriber will have completed the dialling of the thousand's digit before the sending switch has completed the transmission of the series of code impulses, and assuming that this has been done in the present case, when the sending switch S arrives in normal position after the transmission of the final series of code impulses, the deenergization of the stop relay 105 will be effective to again close the circuit of the impulsing relay 107. Since the thousand's digit in the number is digit 2, the wiper 244 of the thousand's register M^1 is now standing on the second contact in its bank, and since the wiper 244 is now grounded by way of the wiper 404 of the sequence switch S^1 , there will be a ground on the No. 2 contact in the bank of the stop wiper 114. It follows that in the next operation of the sending switch S , two interruptions will be produced in the control circuit, similar to the manner in which the several series of code interruptions were produced. These interruptions or impulses are received at the repeater R , Fig. 8, and are repeated over the interoffice trunk line to the incoming selector E^4 in the Torrington office, which operates to raise its wipers opposite the second level, whereupon an idle trunk is selected extending to a third selector which we will assume is the selector E^5 .

During the operation of the sending switch in transmitting the thousand's digit of the number, the stepping magnet 402 of the sequence switch S^1 is energized and deenergized in the usual manner and advances the sequence switch wipers to the sixth or hundred's position. The movement of sequence switch wiper 404 disconnects ground from the wiper 244 of the thousand's register M^1 and connects

ground to the wiper 245 of the hundred's register M^2 by way of conductor 416. Assuming that the calling subscriber has already dialled the hundred's digit 3, the conductor 422 will now have a ground on it, causing the sending switch to restart immediately when the stop relay 105 falls back. Since the hundred's digit in the number is the digit 3, there will now be a ground on the No. 3 contact in the bank of the stop wiper 114 by way of the wiper 245 of the hundred's register, and the sending switch will operate to transmit a series of three impulses. These impulses are repeated by the repeater R, Fig. 8, to the fifth selector E^5 in the Torrington office which raises its wipers to the third level and selects an idle trunk extending to a connector switch, which we will assume to be the connector H .

During the operation of the sending switch in transmitting the hundred's digit in the number, the sequence switch magnet 402 is energized and deenergized in the usual manner in order to advance the sequence switch wipers to the seventh or ten's position. Assuming now that the calling subscriber has completed the dialling of the ten's digit, conductor 423 will be grounded and wiper 246 will be standing on the No. 4 contact in its bank, thus extending a ground to the No. 4 contact in the bank of the sending switch S. A series of four impulses is accordingly transmitted by the sending switch, and is repeated by the repeater R to the connector H in the Torrington office, which accordingly raises its wipers in the well-known manner to the fourth level of bank contacts. The sequence switch magnet 402 is energized and deenergized in the usual manner during the transmission of the impulses corresponding to the ten's digit, and advances the sequence switch wipers to the eighth or unit's position with the result that wiper 404 places a ground on the wiper 247 of the unit's register M⁴. Assuming that the final digit has been dialled by the calling subscriber, conductor 424 will now be grounded, the sending switch S will be started on its final operation and since wiper 247 is in engagement with the No. 5 contact in its bank, a series of five impulses will be transmitted. The last series of impulses is repeated by the repeater R to the connector H which is operated in the usual manner to rotate its wipers into connection with the line extending to the station A¹. Upon the completion of the connection to the called line, a signalling circuit is established in the connector in the usual manner and the bell at the called station is operated to notify the subscriber that he is wanted. In the foregoing explanation it has been assumed each time that when the sending switch arrives at normal position after the transmission of a digit, the calling subscriber has already completed the dialling and registration of the next succeeding digit. It will be understood, of course, that in case there is

any delay on the part of the calling subscriber, the sending switch will eventually catch up with him and that in such a case the restarting of the sending switch will be postponed until another digit has been registered. 70

The energization and deenergization of the sequence switch magnet 402 during the transmission of the final series of impulses causes the sequence switch wipers to be advanced to the ninth or switching position, whereupon the following circuit is established for the switching relay 112: from ground by way of sequence switch wiper 406 in switching position, conductor 420, contacts controlled by armature 139, and the winding 75 of relay 112 to battery. On energizing, relay 112 establishes a locking circuit for itself at armature 139, breaking its initial energizing circuit at the same time, opens the circuit of relay 107 at armature 140, removes the shunt 80 from resistance 141 at armature 137, and at armature 138 disconnects conductor 103 from conductor 202 and connects the former conductor to ground. This latter operation completes a circuit for the switching relay 13 in 85 the first selector trunk as follows: from ground by way of armature 138, conductor 103, bank contact 92, Fig. 1, wiper 88, working contact of armature 83 and the said armature, armature 73 and its working contact, 90 conductor 62, contact springs controlled by armature 16, and the winding of the switching relay 13 to battery. Upon energizing, relay 13 establishes a locking circuit for itself at armature 16, connects the trunk conductors 10 and 12 with trunk conductors 20 and 22, respectively, at armatures 14 and 18, and disconnects the said trunk conductors 10 and 12 from conductors 60 and 61, respectively, 95 at armatures 15 and 17. A special adjustment of the contact springs of relay 13 is essential in order to secure a quiet switching through operation. The relay should be so adjusted that the springs represented by armature levers 14, 16, and 18 engage their working contacts first, as a result of which the calling subscriber's line will be connected to the windings of the line relay of the repeater in multiple with the switch control circuit in the director, and in multiple with 100 line relay 64 of the director selector F. The resistance 141 is inserted in the control circuit by the operation of the switching relay 112 in the director in order to prevent short circuiting of the subscriber's line and the objectionable noise in the receiver which would occur if short circuiting should take place. An instant after armatures 14 and 18 engage their working contacts, the control circuit 105 extending to the director is cut off, and finally, just before the relay is fully operated, armatures 15 and 17 disengage their resting contacts. The latter operation disconnects the line relay 64, and completes the switching 110 operation by which the calling subscriber's 115 line is connected to the line relay 64 of the director selector F. The sequence switch 402 is then 120 returned to its initial position, and the control circuit is again established, so that the sequence switch 402 may be again advanced to the ninth position, and the 125 transmission of the final series of impulses may be again initiated.

line is connected through to the extended portion of the established connection.

When the line relay 64 of the director selector F is disconnected from the trunk by 5 the operation of the switching relay 13, it deenergizes and breaks the circuit of the slow-acting release relay 65, which deenergizes in turn and at armature 75 completes a circuit for the release magnet 71. By the operation 10 of the release magnet the director selector F is restored to normal in the usual manner, the release magnet circuit being opened at the off normal springs when the shaft reaches normal position. On deenergizing, 15 relay 65 also disconnects ground from conductor 76 and from the holding conductor 102. The switching relay 68 in the director selector is accordingly deenergized, as are also the relays 110, 111, and 210 in the director. On deenergizing, relay 111 connects ground to the upper bank of the sequence 20 switch at its armatures 133 in order to advance the sequence switch wipers to their normal position. At the same time at the upper 25 armature 133 the locking circuit of switching relay 112 is broken and this relay is permitted to deenergize. At armature 132 relay 111 connects the wiper 113 of the sending switch S with the stepping magnet 115 through its interrupter contact. This operation, however, is of no particular importance, ordinarily, owing to the fact that the sending switch is restored automatically by 30 the completion of the same circuit at armature 116 of the stop relay. Relay 110, on deenergizing, connects ground to release conductor 204 at armature 130, thus completing parallel energizing circuits for the release magnet 211 of the master digit controller 35 M, the release magnet 305 of the register switch J, and the release magnets 220, 221, 222, and 223 of register switches M¹ to M⁴, inclusive. The several switches mentioned are accordingly restored to normal position 40 in the well understood manner, each switch opening the circuit of its associated release magnet at its off normal springs as soon as it is fully restored. The low resistance relay 45 108 is included in series with conductor 204, and on energizing, disconnects the holding conductor 102 from the local holding conductor 203 and connects the former conductor to ground. This operation places a ground 50 on the test contact 91 and its multiples in the banks of the director selectors such as the director selector F, and prevents seizure of the director while the register switches thereof are returning to normal position. Relay 55 110, on deenergizing, also connects up the high resistance relay 109, the upper winding of which is connected to wiper 113 of the sending switch, while the lower winding is connected to wiper 403 of the sequence switch. When relay 110 falls back, therefore, relay 109 60 65 will be energized, since the sequence switch

S¹ and possibly also the sending switch S are out of normal position, and at armature 127 will prepare a ground for the holding conductor 102. It follows that when the relay 108 falls back on the complete restoration 70 of all the register switches, if the sending and sequence switches are not yet fully restored, the conductor 102 will remain grounded. It may be stated that ordinarily the sending and sequence switches will arrive at normal position at approximately the same time as the register switches are restored, and the relay 109 is provided chiefly to guard against some defect in these switches by which they might be prevented from restoring at all. 80 If one of these switches should get out of adjustment, for instance, and fail to restore, it would render the director completely inoperative, but in such a case relay 109 would be maintained energized in order to keep the 85 trunk extending to the director in busy condition. When either relay 108 or 109 is energized a ground is placed on conductor 498 which may be used to operate some kind of an alarm to signal a switchboard attendant. 90

The contact springs represented by armature 132 and its resting contact are added to relay 111 in order to insure that the sending switch S will be advanced to normal position in case the calling subscriber should hang 95 up his receiver while the sending switch is operating, and before the stop relay 105 is energized. For example, if the calling subscriber should hang up while the director is in use, the line relay 64 will fall back and the director selector F and all the register switches in the director will be restored to normal. If the circuit of the impulsing relay 107 should be broken by the removal of ground from a conductor such as 400 or 421, 100 while the said impulsing relay is operating to transmit impulses before the stop relay 105 is energized, the movement of the sending switch would be stopped and it would remain in an off normal position. However, 105 the provision of the contact springs mentioned prevents such an occurrence, for whenever the director is released relay 111 is deenergized and the said contact springs are effective to connect the wiper 113 to the stepping magnet 115, with the result that the sending switch S is always advanced to normal position no matter whether the calling subscriber hangs up prematurely or not. 110

As described in the foregoing, the connection is switched through and the director is released as soon as the final series of impulses has been transmitted. The director is thus used only during the actual setting up of the connection and is rendered accessible to other subscribers as soon as the connection is completed. After the connection has been switched through it is the same in all essential particulars as any ordinary automatic connection, such as is found in ordinary au- 115 120 125 130

tomatic telephone systems which do not employ directors and is controlled by the calling subscriber in the usual way. When the called subscriber answers the calling and called parties will converse as desired, and will replace their receivers when the conversation is finished. The release of the connection is controlled by the calling subscriber. When the receiver is replaced at the calling station, the line and release relays of the repeater R are deenergized, with the result that the holding circuit for the automatic switches in the originating exchange is broken, and with the further result that the control circuit extending over the interoffice trunk to the Torrington office is broken also. It follows that all of the automatic switches involved in the connection are restored to normal according to well-known practice.

Having explained the process of setting up and releasing a typical connection, it will be desirable now to consider briefly the establishment of several other connections, principally for the purpose of further explaining the operation of the director in transmitting the office codes. In the case just explained, in which the subscriber at station A set up a connection to the subscriber at station A¹, a three-digit office code was used, and a case will now be explained in which a four-digit office code is used. For this purpose it will be assumed that the subscriber at station A desires to extend a connection to the subscriber at station A², whose telephone number is LOTHair 2345. As may be seen from an inspection of the trunking layout, Fig. 8, the trunking of a call to the Lothair office requires the operation of first, second, and third selectors in the originating office and the operation of an incoming fourth selector in the Lothair office, which as before explained is a tandem office. Consequently, a four-digit code is required.

To proceed with the establishment of the connection, when the calling subscriber removes his receiver his line is extended to a first selector trunk as previously pointed out, and it will be assumed that the trunk illustrated in Fig. 1 is the one taken for use. The director selector F now responds to the dialing of the initial letter L of the called number and operates to select an idle director in the fourth group, it being assumed that the director taken for use is the one illustrated in the drawings. The calling subscriber will now dial the letters O and T of the called number, followed by the four digits 2, 3, 4, and 5. The registering equipment in the director operates to register the above letters and digits in precisely the same manner as was described in the preceding case. The register switch J, Fig. 4, is controlled by the line relay 64 of the director selector F and receives two series of impulses, one comprising ten impulses and the other comprising four impulses, in ac-

cordance with which its wipers are raised ten steps to the tenth level, and are then rotated four steps into engagement with the fourth set of contacts. After the registration of the letters O and T, the four digits are registered 70 on the register switches M¹ to M⁴, inclusive, the same as was previously described.

It will be seen that the only respect in which the operation of registering the number LOTHair 2345 differs from the operation 75 of registering the number TORrington 2345, is that the wipers of the register switch J are brought into engagement with the fourth set of contacts in the tenth level rather than the second set. This is sufficient, however, to 80 cause an entirely different trunking operation which will result in trunking the call to the Lothair office rather than to the Torrington office. The desired result is, of course, obtained by properly cross-connecting the 85 terminals 334 to 337, inclusive, on the left-hand side of the I. D. F., which are the terminals selected by the operation of the register switch J, to the bus-bars on the right-hand side of the I. D. F. The proper cross- 90 connections are determined by the arrangement of the trunking, and an inspection of Fig. 8 will show that the code digits 6, 5, and 3 are required to obtain a trunk to the tandem office, after which the incoming fourth selector 95 E⁴⁴ would have to be operated in accordance with the code digit 5 in order to obtain connection with a local fifth selector such as the selector E⁵⁵. The complete office code then is 6535. Accordingly, terminal 337 is 100 cross-connected to bus-bar No. 6, terminal 336 is cross-connected to bus-bar No. 5, terminal 335 is cross-connected to bus-bar No. 3, and terminal 334 is cross-connected to bus- 105 bar No. 5.

When the starting conductor 400 is grounded by wiper 219 of the master digit controller M, the sending switch S begins to operate and transmits three successive series of impulses corresponding to the code digits 110 6, 5, and 3 exactly the same as was done in the preceding case. On the completion of the transmission of the third series of impulses, when the stop relay 105 pulls up the wipers of the sequence switch S¹ will be advanced 115 to fourth position by the deenergization of the stepping magnet 402. In the former case this caused an automatic operation of the sequence switch by means of which it was instantly advanced to fifth or thousand's position, but in the present case a four-digit code is required to be transmitted and no automatic advance of the sequence switch is necessary. The fourth terminal of the set, terminal 334, instead of being connected to 120 bus-bar X is connected to the bus-bar No. 5 and consequently, immediately after transmitting the third series of impulses corresponding to the code digit 3, the sending switch transmits a fourth series of impulses 125 130

corresponding to the code digit 5. Following the transmission of the last code digit, the sequence switch S^1 advances its wipers to fifth or thousand's position, and the four digits of the called number are then transmitted by the sequence switch as registered. The switching through of the connection and the release of the director equipment is the same as in the case previously described, and consequently, will be understood without further explanation.

Using the circuits as illustrated, the maximum number of series of impulses in any code is four, as this is considered to be all that will ever be required in operating systems. In the case of all those exchanges which are reached by way of direct trunks, the codes will never have more than three digits, and in a good many cases may have only two digits. The majority of exchanges which are reached through tandem offices will be accessible through a single office of this character, and consequently, the codes will require not to exceed three digits in the originating office and one in the tandem office, or four in all, as in the case of the code for the Lothair office. It is recognized that there may be cases where it is necessary to employ two tandem offices in serial relation, as for example, when connections are trunked from an exchange on one edge of a network to another exchange on the extreme opposite edge, in which case it may be desirable to so arrange the trunking that the connection will be extended through two tandem offices, as stated. In a case of this character it is generally possible to arrange the trunking so that the first tandem office may be reached on a two-digit code, in other words the trunks extending to the first tandem office are made accessible from the second selectors in the originating office rather than from the third selectors. This would leave two code digits for controlling the tandem trunking, one for each of the two tandem offices involved. In view of the foregoing, it will be evident that the circuits illustrated are sufficient to provide for the different instances of interoffice trunking which are liable to be met with in practice. It is appreciated, however, that in extremely complicated networks the trunking between offices may become so involved that more than four code digits are required. In a case of this kind the circuits of the director are changed by adding as many more wipers and banks to the B and C impulse register J as are required, and by providing additional positions on the sequence switch between the fourth and the thousand's positions.

The operation of the director in transmitting short codes consisting of two digits or only one digit may now be briefly explained. The transmission of these short codes involve the use of the special bus-bars X , Y , and Z

for advancing the sequence switch automatically on the completion of the code, and these operations are all that need be considered. It was explained before in the course of the detailed explanation of the operation of the director, how the bus-bar X was made use of to automatically advance the sequence switch through its fourth position when a three-digit code is being transmitted. In the case of a two-digit code bus-bar X is made use of in the same way as before, and in addition bus-bar Y is used. For instance, and assuming that the conductors which are connected to terminals 342 to 345, inclusive, are associated with an exchange requiring a two-digit code, the terminals 345 and 344 are cross-connected to certain numerical bus-bars, such as the bus-bars 8 and 7, terminal 343 is cross-connected to bus-bar Y , while terminal 342 is cross-connected to bus-bar X . When a number in the exchange corresponding to this set of terminals is called, the sending switch S will be started and will transmit two series of impulses corresponding respectively to the code digits 8 and 7, whereupon the sequence switch S^1 will be advanced to third position. Since terminal 343 is cross-connected to bus-bar Y , a circuit is completed including conductor 413, wiper 308, terminal 343, bus-bar Y , and conductor 371 by means of which the stepping magnet 402 is operated momentarily to advance the sequence switch wipers to fourth position, whereupon a similar circuit is immediately completed including the upper register switch wiper 309 and bus-bar X by means of which the sequence switch magnet 402 is again operated momentarily to advance the wipers to fifth or thousand's position.

The scheme for cross-connecting to produce any required number of series of impulses will now be readily appreciated. Considering any particular set of four terminals on the left-hand side of the I. D. F., if it is desired to cross-connect these terminals so as to produce a four-digit code, all four terminals are cross-connected to the proper numerical bus-bars on the right-hand side of the I. D. F.; if it is desired to produce a three-digit code the first three terminals are connected to the proper numerical bus-bars, while the fourth terminal is connected to bus-bar X ; if it is desired to produce a two-digit code the first two terminals are cross-connected to numerical bus-bars, while the third and fourth terminals are cross-connected to bus-bars Y and X , respectively; and if it is desired to produce a one-digit code, which may be necessary in some cases, the first terminal is cross-connected to a numerical bus-bar, while the second, third, and fourth terminals are cross-connected to bus-bars Z , Y , and X , respectively. Of course, if it is known definitely that a single digit code will never be required, bus-bar Z can be omitted.

An exception to the above directions for

cross-connecting to produce the various codes occurs in the case of a code which includes the digit 0. For instance, if it is desired to cross-connect the terminals 338 to 341, inclusive, so as to transmit the office code 650 instead of the office code 654, terminals 341 and 340 are cross-connected to bus-bars 6 and 5, respectively, terminal 339 is left dead, and terminal 338 is cross-connected to bus-bar X. The omission of the cross-connection from terminal 339 is made possible by the grounding of the No. 10 contact in the bank of the stop wiper 114, which causes the sending switch to transmit ten impulses in all cases unless the stop wiper is energized at the proper point to produce a shorter series of impulses. Thus the sending switch will automatically send a maximum of ten impulses and whenever it is desired to produce a series of impulses containing the maximum number no cross-connection at the I. D. F. is necessary.

The operation of the director in handling regular traffic having been described, its operation in trunking calls to the various special operators will now be taken up. The first case which will be considered is the calling of the complaint operator, who is reached by dialing the first three letters C, O, and M of the word complaint. Assuming that the calling subscriber is the party at station A as in the preceding cases, and that the first selector trunk equipment illustrated in Fig. 1 is taken for use, when the first letter C is dialled the director selector F will respond and raise its wipers to the fourth level, after which a trunk line extending to an idle director equipment will be automatically connected with. Assuming that the director illustrated in Figs. 2 to 5, inclusive, is selected for use, when the calling subscriber dials the letters O and M, the line relay 64 of the director selector will transmit two corresponding series of impulses to the B and C impulse register J and this switch will be operated to raise and rotate its wipers into engagement with the fifth set of contacts in the tenth level. Only the three letters named are dialled, and consequently, none of the register switches M¹ to M⁴, inclusive, are operated. the master digit controller M remaining in third position after the dialling of the last letter M. The sending switch S is now set in motion in the usual manner by the grounding of start wire 400 to transmit impulses in accordance with the particular code which is required to trunk the call to the complaint operator. This code, it may be seen from Fig. 8, is the two-digit code 60. In order to secure the transmission of this code, and in order to switch the connection through when the transmission of the final code digit is completed, the terminal 333 is cross-connected to bus-bar No. 6, terminal 332 is left dead, and terminal 331 is cross-connected to the switching bus-bar Sw¹. In view of these

cross-connections, when the sending switch S is started, it first transmits a series of six impulses, followed by a series of ten impulses, from which it will be understood that the first selector E¹ is raised to the sixth level, and that a second selector such as the second selector E² is raised to the tenth level. The last mentioned selector then automatically selects a trunk extending to the complaint operator's position, such as the one indicated in the drawing which terminates in the jack J. In the director on the completion of the transmission of the second code digit, the sequence switch wipers will be advanced to third position, whereupon a circuit will be completed for the switching relay 120 as follows: from the grounded conductor 400 by way of wiper 404 in third position, conductor 413, wiper 308 and bank contact engaged thereby, terminal 331, a jumper connecting said terminal with the switching bus-bar Sw¹, conductor 373, sequence switch wiper 406 in third position, conductor 420, contact springs controlled by armature 139, and the winding of switching relay 112 to battery. On the energization of the switching relay 112, the switching relay 13 in the selector trunk is operated as previously explained, the calling line is switched through and the director is released in the usual manner. Suitable equipment is provided in the trunk extending to the jack J to provide a holding circuit for the switches involved in the connection, and to provide for signalling the operator when the trunk is taken for use. The complaint operator is provided with suitable means such as cord circuits of well-known type and construction for answering calls arriving at her position, and on receipt of the call in question she will respond by plugging in the jack J with one of these cord circuits. The conversation will now take place in the usual manner, and when the calling subscriber is through he will hang up his receiver and release the connection.

It will be observed that in the foregoing case the establishment of the complete connection requires the transmission of only two series of impulses, and the operation of only two selector switches, and it will be noted further that the call is switched through after the final series of impulses has been transmitted without the use of any special relays or equipment whatever beyond the special switching bus-bar Sw¹. It may be stated that the circuits shown provide for switching through automatically after the transmission of any special number of the character described which does not contain more than three digits. The number is limited to three, because one of the terminals of any set corresponding to a special number must be cross-connected to switching bus-bar Sw¹ in order to switch the call over after the transmission of the final series of code impulses. The

maximum number of code impulses which can be transmitted on regular calls is 4, corresponding to the number of terminals in each terminal set and the number of wipers of the 5 register switch J, but in transmitting special numbers, which must be switched over after the transmission of the last series of code impulses, one of the terminal sets has to be used to control the switching at the proper time, and 10 consequently, one series of impulses must be sacrificed in order to provide for switching.

Three series of code impulses is sufficient in all cases where the operator's position is located in the same exchange, as is almost 15 always the case with the complaint operator, wire chief, and possibly some others. There are certain operators, however, such as the information operators and the long distance operators which according to standard practice are generally located at some central 20 point in the system to which all calls for these operators are trunked regardless of where they originate. Calls to the long distance operator are taken care of by a special 25 group of directors such as the one shown in Fig. 6, the operation of which will be described shortly, but calls to the information operator must be taken care of by the regular directors in group 4, because the information 30 operator is obtained by dialling the first three letters I, N, and F of the word information. Referring now to the trunking layout, Fig. 8, it will be assumed that the information and long distance operators are located 35 in a special office which is accessible to subscribers in the West office by way of the Lothair tandem office. The code for trunking an information call to its proper destination is made up of the code digits 6, 5, and 40 3, which trunk the call to the tandem office, the code digit 3 which will trunk the call through the tandem office by way of the third level of the incoming selectors such as the incoming selector E⁴, and the code digit 2, 45 which will serve to operate an incoming fifth selector in the special office to extend the call to the information operator's switchboard. According to this the complete code for information is 65332.

50 As explained in the preceding paragraph, the code in accordance with which information calls are trunked to the operator is composed of five digits, from which it will be seen that it will be impossible for a regular director such as the one illustrated to transmit this code without some special arrangement. In order to provide for this unusual case, therefore, a special relay 430, Fig. 5, is provided, the operation and function of 55 which will now be pointed out, it being assumed for this purpose that a subscriber in the West office desires to call the information operator. As in the preceding cases, it will be assumed that the call originates with the 60 subscriber at station A, whose line is ex-

tended when the receiver is removed to a first selector trunk equipment in the usual manner. Assuming that the trunk equipment shown in Fig. 1 is taken for use, when the first letter I of the word information is 70 dialled, the director selector F is caused to raise its wipers to the first level, and since the first level is connected in multiple with the fourth level, the director selector operates to select and connect with an idle director equipment in the fourth group. Assuming that the director taken for use is the one shown in Figs. 2 to 5, inclusive, when the calling subscriber dials the second and third letters N and F the B and C impulse 80 register switch J will be operated to raise its wipers six steps in a vertical direction and then seven steps in a rotary direction, the wipers being finally brought to rest in engagement with the seventh set of contacts 85 in the sixth level. This set of contacts is not shown in the drawing, but it will be assumed that a set of four conductors connects this set of contacts with terminals 346 to 349, inclusive, on the left-hand side of the I. D. F., 90 similar to the manner in which the bank contact sets which are shown are connected. As soon as the register switch J has completed its operation, conductor 400 is grounded at the master digit control switch M in 95 the usual manner and the sending switch S is set in motion. Since terminals 349, 348, and 347 are cross-connected to bus-bars No. 6, No. 5, and No. 3 respectively, the said sending switch will transmit three series of 100 impulses, the first series consisting of six impulses, the second series consisting of five impulses, and the third series consisting of three impulses. Responsive to these three series of impulses the call is trunked to the 105 Lothair tandem office by way of the first selector E¹ and second and third selectors such as the second and third selectors E² and E³.

Following the transmission of the third series of impulses, the wipers of the sequence switch S¹ are advanced to fourth position, and now since terminal 346 is cross-connected to the special bus-bar RL, a circuit is completed for relay 430 as follows: from the grounded conductor 400 by way of wiper 404 in fourth position, conductor 414, wiper 309 of register switch J and bank contact engaged thereby, terminal 346, a jumper connecting this terminal with bus-bar RL, conductor 374, contact springs controlled by armature 431, and the winding of relay 430 to battery. Upon the completion of the above circuit, relay 430 is energized and establishes a locking circuit for itself at armature 431, the initial energizing circuit being broken at the same time. In addition to the foregoing, at armatures 434, 433, and 432 relay 430 connects conductors 414, 415, and 416, coming from the 125 fourth, fifth, and sixth contacts in the bank 130

- of sequence switch wiper 404, to conductors 442, 441, and 440, respectively, which are connected to terminals 356, 355, and 354, respectively, on the left-hand side of the I. D. F. In addition, relay 430 connects the conductor 375 coming from the switching bus-bar Sw^2 to conductor 436 at armature 435. Terminal 356 is cross-connected to bus-bar No. 3, and consequently, on the next operation of the sending switch S, a series of three impulses will be transmitted which are repeated over the interoffice trunk line to the tandem office by the repeater R^1 , and which operate the incoming selector E^{44} to trunk 70 the call to the special office in which the information operator's switchboard is located. Following this series of impulses sequence switch S^1 advances its wipers to fifth position in the usual manner, and since terminal 75 355 is cross-connected to bus-bar No. 2, the sending switch S on its next operation will transmit a series of two impulses. This final series of impulses is repeated by the repeaters R^1 and R^4 to the incoming selector 80 25 E^{555} which operates to raise its wipers to the second level, after which an idle trunk is selected which extends to the information operator's switchboard, such as the one extending to the jack J^2 , for example. 85 30 Following the transmission of the final series of impulses the wipers of the sequence switch S^1 are advanced to sixth position, and since terminal 354 is cross-connected to the switching bus-bar Sw^2 , a circuit is completed 90 25 for the switching relay 112 as follows: from the grounded conductor 400 by way of wiper 404 in sixth position, conductor 416, armature 432 and its working contact, conductor 440, terminal 354, a jumper connecting this 95 40 terminal with switching bus-bar Sw^2 , conductor 375, working contact of armature 435 and said armature, conductor 436, wiper 406 in sixth position, conductor 420, and the winding of the switching relay 100 45 112 to battery. On energizing, relay 112 closes a circuit for the switching relay 13 in the first selector trunk in the usual manner, and the calling line is connected through to the extended portion of the connection the 105 50 same as described in the preceding cases, the director equipment being restored to normal and rendered accessible to other calls. 110 Another instance of a long special code is found in the case of the operator who handles 55 the so-called "dead number" calls. As will be understood, there may be a large number of contact sets in the bank of the register switch J which do not correspond to working exchanges, and it is desirable to arrange 115 for trunking calls accidentally arriving at these contact sets to an operator, in order that the subscribers may be notified that they are not getting anywhere and thus be saved the annoyance and loss of time which would otherwise result. In order to take care of 120 60 125 65 130 this properly the dead contact sets in the bank of the register switch J are preferably multiplied together as is shown in the case of the first and third contact sets in the tenth level and are connected to terminals 350 to 70 353, inclusive, on the left-hand side of the I. D. F. If the dead number calls are handled by the complaint operator, as will often be the case, this set of terminals is cross-connected the same as the set of terminals 330 to 333, inclusive, is cross-connected, or if the dead number calls are handled by some other operator having a switchboard located where it is accessible by means of a three-digit code, the set of terminals in question is cross-connected in a similar manner. If the operator who handles the dead number calls is located in the same office with the information operator, however, the above method of cross-connection will not answer, and a 80 85 special relay similar to the relay 430 will have to be provided. From the detailed explanation of the operation and function of relay 430 in trunking calls to the information operator, it is thought that the method of connecting a similar relay to trunk dead number calls to the proper operator will be understood without difficulty. 90 95 100 105 110 115 120 125 130
- As stated hereinbefore, calls to the long-distance operator are handled by a group of special directors such as the director illustrated in Fig. 6, and the establishment of a connection of this kind will now be explained. Assuming that the party at station A desires to place a long distance call, he will remove his receiver and then operate his calling device in accordance with the digit 0. On the removal of the receiver the calling line is extended to a first selector trunk in the usual manner, and assuming that the trunk shown in Fig. 1 is the one taken for use, when the digit 0 is called the director selector F will be operated to raise its wipers ten steps opposite the tenth level of bank contacts. On the completion of the vertical operation of the director selector its automatic trunk hunting movement is initiated, and the wipers are rotated step by step in search of an idle director. Assuming that the director illustrated in Fig. 6 is the first idle one in the group, when the wipers arrive at bank contacts 93 to 96, inclusive, the trunk hunting movement of the director selector will cease and switching relay 68 will be energized. At armature 84 relay 68 connects ground to the test wiper 87 and to the test contact 95, thus making the selected director busy. At armature 83 the conductor 62 is connected by way of wiper 88 and bank contact 96 with conductor 503. At armatures 81 and 82 conductors 25 and 26 are extended by way of wipers 85 and 86 to conductors 500 and 501, respectively, and a bridge is closed across the trunk conductors 20 and 22 which may be traced from trunk conductor 20 by 120 125 130

way of normally closed contact springs controlled by armature 14, conductor 25, working contact of armature 81 and said armature, wiper 85, bank contact 93, conductor 500, armature 519 and its resting contact, resting contact of armature 552 and said armature, conductor 501, bank contact 94, wiper 86, armature 82 and its working contact, and normally closed contact springs controlled by armature 18 to trunk conductor 22. The closure of the above traced bridge completes the control circuit from the sending switch S^2 of the director, Fig. 6, to the line relay 30 of the selector E^1 and the said line relay is energized. Relay 30 closes a circuit for the slow-acting release relay 31, whereupon the selector E^1 is prepared for operation in the usual manner.

When ground is placed on the test wiper 87 and test contact 95 by the energization of the switching relay 68 in the director selector F , the holding conductor 502 is grounded and a circuit is completed for relay 506. On energizing, relay 506 disconnects ground from the upper bank of the sequence switch S^3 at armature 511, disconnects relay 505 at armatures 512 and 513, disconnects wiper 540 of the sending switch S^2 from the stepping magnet 590 at armature 515, and at armature 514 connects the grounded holding conductor 502 to the wiper 509 of the sequence switch S^3 . At the same time a circuit is completed for the impulsing relay 544 of the sending switch S^2 which extends from the grounded conductor 502 by way of the working contact of armature 514 and said armature, armature 518 and its resting contact, resting contact of armature 548 and said armature, winding of the impulsing relay 544, and the interrupter I^1 to battery. The establishment of the latter circuit initiates the operation of the sending switch S^2 .

The connections at the intermediate distributing frame may now be considered briefly. An inspection of the trunking layout, Fig. 8, will show that the code required to trunk calls from the West office to the long distance operator is composed of five digits, the digits 6, 5, 3, 3, and 3; accordingly, the first terminal 571 on the upper side of the frame is cross-connected to bus-bar No. 6 on the lower side of the frame, terminal 572 is cross-connected to bus-bar No. 5, and terminals 573, 574, and 575 are cross-connected to bus-bar No. 3. Terminal 576, it may be mentioned, is cross-connected to the switching bus-bar Sw^3 in order to take care of switching the call through after the required number of series of impulses have been transmitted.

The operation of the sending switch S^2 may now be considered briefly. When the circuit of the impulsing relay 544 is completed by the energization of relay 506 as explained hereinbefore, the said relay begins

operating intermittently under the control of the interrupter I^1 , and transmits impulses to the stepping magnet 590 by means of which the wiper 540 and the stop wiper 541 are advanced step by step. On the first step of the switch, wiper 540 engages a grounded contact, and a circuit is completed for relay 543. On energizing, relay 543 removes the shunt from impulsing contacts 552 at armature 550 in order to permit the impulsing relay 544 to transmit impulses, prepares a locking circuit for stop relay 542 at armature 551, and at armature 549 closes a circuit for the stepping magnet 591 of the sequence switch S^3 . The sequence switch magnet is accordingly energized. When the stop wiper 541 of the sending switch arrives at the No. 6 contact in its bank, it will find a ground potential and stop relay 542 is energized. On energizing, relay 542 completes a locking circuit for itself at armature 547, breaks the circuit of impulsing relay 544 at armature 548 in order to stop the transmission of impulses, closes an automatic rotary circuit for the stepping magnet 590 at armature 545, and at armature 546 breaks the circuit of the sequence switch magnet 591. By the completion of the automatic rotary circuit the wipers of the sending switch are advanced to normal position, while the interruption of the circuit of the sequence switch magnet 591 permits the said magnet to deenergize and advance the sequence switch wipers to second position. Having transmitted the first series of impulses, the sending switch S^2 continues to operate automatically and transmits four other series of impulses, the second series consisting of five impulses, while the third, fourth, and fifth series consist of three impulses each. In response to these series of impulses the proper automatic switches are operated to trunk the call to the long distance operator's switchboard in the special office, the call being extended to a trunk line terminating in a jack such as the jack J^1 . Fol-

lowing the transmission of the final series of impulses the wipers of the sequence switch S^3 will be advanced to sixth position, whereupon a circuit is completed for the switching relay 507 which extends from the grounded wiper 509 in sixth position by way of terminal 576, a jumper connecting this terminal with the switching bus-bar Sw^3 , conductor 560, and the winding of relay 507 to battery. On energizing, relay 507 completes a locking circuit for itself at armature 517, breaks the circuit of impulsing relay 544 at armature 518, inserts the resistance 520 in the switch control circuit at armature 519, and at armature 516 completes a circuit over conductor 503 for the switching relay 13 in the first selector trunk. On energizing, the switching relay 13 connects the calling line with the extended portion of the connection in the usual manner, and the director is released and re-

turned to common use. The release of the director is brought about by the removal of ground from the holding conductor 502, which permits relay 506 to fall back. On de-
 6 energizing, relay 506 connects the wiper 540 of the sending switch with the stepping mag-
 net 590 at armature 515 in order to insure the return of the sending switch to normal, and at armature 511 connects ground to the bank
 10 associated with the wiper 508 of the sequence switch S^3 in order to advance the sequence switch to normal position. In addition, relay 506 connects the upper and lower wind-
 15 ings of relay 505 to wipers 540 and 508 of the said two switches, respectively, and thus brings about the energization of relay 505, which remains in operative position until both the sending switch and the sequence switch have advanced their wipers to normal position.
 20 Relay 505 operates similar to relay 109 of the regular director, and opens the holding conductor 502 at armature 510 and connects the incoming section thereof to ground in order to make the director busy and maintain it in this condition until the
 25 switches are fully restored.

It will be noticed that the long distance director is very similar to the regular director such as is illustrated in Figs. 2 to 5, in-
 30 clusive, but is much simpler on account of the fact that it only has to handle a single class of connections. Consequently, all the equipment in the regular director which is not required for handling long distance calls
 35 is omitted, and the construction is correspondingly simplified. It will usually be found advisable to provide an intermediate distributing frame in order to permit the long distance code to be changed readily, but
 40 the intermediate distributing frame is not ab-
 45 solutely required, however, and can be dis-
 pensed with much more easily than it could be in the case of the regular directors where it is considered to be essential. If it is de-
 50 sired to omit the intermediate distributing frame in order to save cost, wires can be run directly from the bank of wiper 509 of the sequence switch S^3 to the bank of the stop wiper 541 of the sending switch.

55 Several special features of the regular director shown in Figs. 2 to 5, inclusive, will now be explained, and the first of these to be considered involves the function and opera-
 60 tion of the time limit control relays 205 and 206, Fig. 2. The directors are installed on a percentage basis, the number required being calculated on the assumption that they will be used only during the actual setting up of connections, and consequently, it is important to
 65 avoid any circuit conditions which could re-
 70 sult in the tying up of directors indefinitely. The class of incompletely calls which are known as "permanents", caused by the grounding or short circuiting of subscribers' lines or by the failure to replace receivers at

70 called stations, of course never reach the directors, because the directors are inaccessible except on the actual dialling of the first letter in a called number. But there is a certain class of incompletely calls, including calls
 75 where the subscriber accidentally leaves out a letter or digit, which never arrive at the switching through stage, and which in any working exchange would cause a certain number of directors to be tied up unnecessarily if special provisions were not made to take care of them. This is the function of the time limit control relays 205 and 206. As pointed out hereinbefore, when the director shown is taken for use and ground is placed on the holding conductor 203, relay 210 is energized and prepares circuits for relays 205 and 206 at armatures 209 and 217, respectively. The timer cam T is mounted on a constantly rotat-
 80 ing shaft which makes one complete rotation every thirty seconds, and consequently, as soon as this cam grounds the conductor 299 a circuit is completed for relay 205, which energizes, and at armature 213 closes a circuit for relay 206. Relay 206 is short circuited, how-
 85 ever, and does not energize until in the con-
 90 tinued movement of the cam ground is re-
 95 moved from conductor 299, whereupon relay 206 is energized in series with relay 205. On energizing, relay 206 connects conductor 299 with conductor 201 at armature 214. It will be observed that the circuit by which relays 205 and 206 are maintained energized includes the back contact of armature 215 of the series relay 207, from
 100 which it follows that if the calling subscriber should dial another digit shortly after relay 206 has pulled up, the circuit of relays 205 and 206 will be broken and these relays will be deenergized. However, if the calling subscriber should fail to dial another digit be-
 105 fore thirty seconds has elapsed, when the timer cam T again grounds conductor 299 relay 206 will be in operated position, and a ground will be placed on conductor 201. Con-
 110 ductor 201 is connected to conductor 420, from which it will be seen that when the said conductor 201 is grounded, as explained, the switching relay 112 will be energized. The energization of relay 112 is followed by the en-
 115 ergization of the switching relay 13 in the first selector trunk, and the director is re-
 120 leased and restored to common use in the usual manner. The calling line is left in connec-
 125 tion with the first selector trunk and whatever portion of the desired connection may have been established, the incompletely call being indicated to the switchboard attendant by means of the usual supervisory signals.

The second special feature also has for its object the minimizing of the time during which the directors are held by the subscribers. In setting up a connection the use of a director is essential only for translating the letters which have to do with the office selec-

tion into a code and for transmitting the code digits, for the numerical digits of the numbers are not translated but are sent out the same as they are registered by the calling subscriber. It will be appreciated, therefore, that if the director should catch up with the calling subscriber after the code digits have all been transmitted, the connection could be switched through in order to permit the rest 10 of the switches involved in the connection to respond directly to the subscriber's dial, thus returning the director to common use somewhat before the time at which it would ordinarily be set free. This scheme involves the 15 use of the key K, Fig. 2, which may be operated and left in that condition in order to take care of switching through under the circumstances mentioned.

Assuming that the director shown is being 20 used by the subscriber at station A to set up a connection to the subscriber at station A¹ for example, and that the key K is in operated position, when the sending switch S has completed the transmission of the three series of impulses corresponding to the office code, the sequence switch wipers will be advanced to the fifth or thousand's position. When this occurs, if the calling subscriber has not yet dialled the first numerical digit of the called 25 number, or the digit which is registered by the register switch M¹, a circuit is completed from ground by way of the off normal spring 236 and its back contact, springs of key K, conductor 401, resting contact of armature 435 and said armature, conductor 436, wiper 406 in fifth or thousand's position, conductor 420, and the winding of the switching relay 112 to battery. Relay 112 is accordingly energized, followed by the energization of relay 13 in 30 the first selector trunk, with the result that the calling line is switched through in the usual manner, except that in the present case the connection is only partially established. The remainder of the switches required to 35 complete the connection to the called line are controlled directly by the calling device at the calling station. It will be understood, of course, that in the preceding case if the calling subscriber had already registered the first 40 numerical digit in the number by the time that the sequence arrived in fifth position, this digit and the other digits in the number would be transmitted by the sending switch in the usual manner.

45 Certain modifications of the system will now be explained, attention being first directed to the modifications illustrated diagrammatically in Fig. 9. The saving in cost accomplished by arranging the directors in 50 groups, as shown in Fig. 8, is due to the substitution of a trunking operation for a letter registration in the director, and the relatively large saving is due to the great difference in the amount of equipment required to register 55 three letters and the amount required to regis-

ter two letters. In the former case a 10 point switch and ten 100 point Strowger switches are required, while in the latter case only a single 100 point Strowger switch is necessary. It should be borne in mind that although the term "register" is used herein for convenience, a mere registration of the letters is not sufficient. The letters could be registered by means of three 10 point switches, but since a translation is necessary, what must be done is 75 to select any one of a thousand possible combinations responsive to three successive series of impulses corresponding to three letters. As stated, in order to accomplish this result a 10 point switch and ten Strowger switches are 80 required.

Further consideration will demonstrate that the grouping or preliminary trunking idea can be carried further than is done in Fig. 8. For instance, another group of 85 selectors on the order of second selectors could be introduced between the director selector F and the directors, which latter will then require means for registering only one letter instead of two. This arrangement would permit the substitution in each director of a simple 10 point switch for the 100 point Strowger switch, and would also reduce the size of the I. D. F. Carrying the idea still 90 farther, third selectors could be introduced between the second selectors and the directors, in which case the directors would be required to register no letters at all, and the directors in each group could be set for a particular 95 office.

Fig. 9 is intended to illustrate the trunking involved in the modifications pointed out above. The director selector F has access on 100 certain of its working levels, such as the second, third, fifth, and sixth levels, to directors such as the director 700, the same as is illustrated in Fig. 8. A group of dead level directors such as the director 701 are accessible from the eighth and ninth levels, while a group of long distance directors such as the director 702 are accessible from the tenth level. The trunk lines from the fourth and seventh working levels, instead of extending directly to directors, extend to second selectors such as the selectors P and P¹. In the 105 group of second selectors including the second selector P, the first, fifth, and ninth levels are assumed to be dead levels and are multiplied together and connected with a group of dead level directors such as the director 701. The working levels including the second, third, fourth, sixth, seventh, eighth, and tenth levels contain terminals of trunk lines extending 110 to groups of directors such as the director 710. In order to save room only two of these groups are indicated in the drawing. The directors which are accessible to the second selectors such as the second selector P are 115 of the type in which means is provided for registering only a single letter, which deter-

mines the office code. In the case of the group of second selectors including the second selector P^1 , the first, third, fourth, seventh, eighth, ninth, and tenth levels are assumed 5 to be dead levels and are multiplied together and connected with a group of dead level directors such as the director 701². The second, fifth, and sixth levels are assumed to be working levels. It is assumed further that there 10 is only one exchange which is accessible from the second level, the trunk lines from which accordingly extend directly to a group of directors such as the director 710¹, which are similar to the directors 710 accessible to the 15 second selector P . There is a plurality of exchanges accessible from each of the fifth and sixth levels, however, and the trunk lines from these levels accordingly extend to groups of third selectors such as the third selectors Q and Q^1 . The bank connections in the latter group of selectors only being indicated in the drawing. The first, second, fourth, fifth, sixth, eighth, ninth, and tenth levels are assumed to be dead levels, are multiplied 20 together, and are connected with trunk lines extending to dead level directors such as the director 701². The third and seventh levels are assumed to be working levels and contain terminals of trunk lines extending to 25 groups of directors such as the director 720. The director 720 of the third group requires no registering means beyond the four minor switches for registering the numerical digits, and so far as the office code is concerned, these 30 directors are set to the particular code which corresponds to the single office with which they are associated. The directors in the seventh group are the same as those in the third group, except that they are set for a different office code.

Various other modifications and combinations of the trunking scheme shown in Fig. 9 45 may be used as the occasion demands, it being understood that the particular trunking arrangement illustrated and described is intended only as an example of the possibilities of the idea. In determining on what arrangement should be employed, in any given case, the entire system would have to be considered 50 from a number of standpoints and a combination chosen which would be the most economical.

Figure 10 shows a modification of the first selector trunk equipment illustrated in Fig. 8. The director selectors such as the director selector F are in use only during the actual 55 setting up of connections, as are the directors themselves, and consequently, in any given system the number of director selectors required will be considerably less than the number of first selector trunks. In view of this fact a small saving can generally be effected 60 by introducing line switches between the first selector trunks and the director selectors, thus making the latter common to the trunks.

The scheme is shown diagrammatically in Fig. 10, wherein the reference characters C^1 , C^2 , D^1 , E^{11} , and F^1 represent the same or similar pieces of equipment as are indicated in Fig. 8, by reference characters C^1 , C^2 , D , E^1 , 70 and F , respectively. The first selector trunk extending from the bank of the secondary line switch C^1 to the first selector E^{11} is provided with the individual line switch C^5 , which has access to a group of director selectors such as the director selector F^1 . 75

Detailed circuits required for operating the system on the plan shown in Fig. 10 are shown in Fig. 7. An inspection of this drawing will render it apparent that the circuit 80 arrangements for the trunk relay equipment D^1 and the director selector F^1 are very similar to the circuit arrangements for the trunk relay equipment D and the director selector F in Fig. 1, while the circuit of the first selector E^{11} is identical with the circuit of the first selector E^1 . In view of this, it will be unnecessary to enter into a detailed explanation of the circuits showing Fig. 7, but it is thought that it will be sufficient to describe 85 briefly the operation of the additional piece of equipment, line switch C^5 . When a calling line is extended to the trunk shown in Fig. 7, the line relay 620 will be energized over the two sides of the calling line in series in the 90 usual manner. On energizing, relay 620 disconnects the operating conductor 670 from ground at armature 610, and at armature 611 closes a circuit for the slow-acting line relay 622. On energizing, relay 622 connects 100 ground to the release trunk conductor 604 at armature 625, in order to provide a holding circuit for the primary and secondary line switches involved in the connection, closes a circuit for the switching relay 623 in series 105 with the stepping magnet 624, at armature 639, and at armature 626 connects the test wiper 633 to the above circuit at a point between the winding of the switching relay and the winding of the stepping magnet. If the 110 trunk with which the wipers of the line switch are now associated is busy, there will be a ground on the test contact with which the test wiper 633 is in engagement, the switching relay 623 will be short circuited, and the stepping magnet 624 will be operated to advance 115 the switch wipers into engagement with the next trunk line. If the next trunk line is busy, the same operation will be repeated and the stepping magnet 624 will continue to operate in the manner of a buzzer to advance the switch wipers step by step until an idle trunk line is encountered. However, if the trunk line with which the wipers of the line switch are associated is idle, there will be no ground 120 potential on the test contact engaged by the test wiper 633, and the switching relay 623 will not be short circuited, but will be immediately energized in series with the stepping magnet 624, the said magnet remaining 125 in-

operative due to the high resistance of the switching relay. Assuming that when the line relay is energized in the present case the director selector F^1 is idle, then switching relay 623 will be immediately operated when its circuit is completed by the said line relay, as pointed out under the second alternative above. Upon attracting its armature 629 relay 623 connects ground to the test wiper 633, and thus makes the trunk line extending to the director selector F^1 busy. In addition to the foregoing, at armatures 630, 627, and 628 conductors 670, 671, and 672 are extended to wipers 634, 631, and 632, respectively, and thence by way of bank contacts 638, 635, and 636 to conductors 660, 661, and 662, respectively, which extend to the director selector F^1 . When the test contact 637 is grounded a ground is placed on the holding conductor 663 and a circuit is completed for the release relay 650 of the director selector F^1 , which attracts its armature and opens the circuit of the release magnet 656.

When the calling subscriber operates his calling device in accordance with the first letter in the called number, the line relay 620 is deenergized a plurality of times, and at armature 610 transmits impulses by way of conductor 670, working contact of armature 630 and the said armature, wiper 634, bank contact 638, conductor 660, armature 657 and its resting contact, winding of the slow-acting series relay 652 to the vertical magnet 651, which is operated in the usual manner to raise the wipers 691 to 694, inclusive, step by step opposite the level in which are terminated trunk lines extending to the desired group of directors. During the vertical movement of the switch the slow-acting series relay 652 maintains its armature attracted, and at the first upper movement of the shaft completes a circuit for the stepping relay 653. On energizing, the latter relay closes a locking circuit for itself at its upper armature, and at its lower armature prepares a circuit for the rotary magnet 655. At the end of the vertical movement of the switch, relay 652 falls back and completes the circuit of the rotary magnet 655, thus initiating the automatic trunk hunting operation of the selector. The wipers 691 to 694, inclusive, are now rotated step by step by the rotary magnet 655 under control of the test wiper 693 and the stepping relay 653 in search of an idle trunk line. When an idle trunk line is encountered, as indicated by the ungrounded condition of the test contact engaged by the test wiper 693, the rotary movement of the selector will cease and the switching relay 654 will energize in the usual manner. Assuming now that the wipers have been raised opposite the fourth level, and that the set of contacts in the fourth level which is indicated in the drawing, is the first set encountered which is found in idle condition, when the switching relay 654 energizes

the grounded holding conductor 663 will be extended by way of wiper 693 and test contact 91¹ to a holding conductor such as conductor 102¹, this operation being effective to ground test contact 91¹ and its multiples 70 and render the selected director busy. At the same time the operating conductor 660 and conductors 661 and 662 are extended by way of wipers 694, 691 and 692, and bank contacts 92¹, 89¹, and 90¹ to conductors 103¹, 100¹, and 75 101¹, respectively. The conductors 100¹ to 103¹, inclusive, extend to and terminate in a director similar to the one shown in Figs. 2 to 5, inclusive, or if desired, it may be assumed that they extend to the same director. The 80 remainder of the operations accordingly, will be understood without further explanation.

The modification illustrated in Fig. 11 is suitable for use in smaller systems, and is produced from the system illustrated in Fig. 10 by omitting the director selectors such as the director selector F^1 . Only one type of director is employed and these directors are rendered directly accessible to the line switches such as the line switch C^s . In explanation of the utility of a system of this character, it may be pointed out that in a good many multi-office telephone systems such as are found in exchange areas of moderate size there will never be more than one hundred offices. In a case of this kind it will be necessary to include in the telephone numbers only the first two letters of the exchange names rather than the first three letters, and office codes are selected in accordance with 90 two letters instead of three. The detailed circuits of this system have not been shown for they are the same as the circuits shown in Fig. 7, except for the fact that the director selectors such as the director selector F^1 100 are omitted, and the line switches such as the line switch C^s are given access to trunk lines extending to directors instead of trunk lines extending to director selectors. For instance, the line switch C^s instead of having access to trunk lines such as the one comprising conductors 660 to 663, inclusive, may be given access to trunk lines such as the one comprising conductors 100¹ to 103¹, inclusive. The 105 directors have the same circuit arrangement 110 as is shown in Figs. 2 to 5, inclusive.

The object and scope of the invention having been described, what is considered to be new and what it is desired to have protected by Letters Patent will be pointed out more 120 specifically in the appended claims:

What we claim is:

1. In a telephone system, a director selector responsive to the initial digits in called numbers, a plurality of directors accessible to said director selector, a series of switches, and means in one of said directors operated automatically responsive to the seizure of such director for trunking the calling line through said series of switches to an 125 130

operator, the connection being established over a path excluding said director selector.

2. In a telephone system, a director, means including an automatic directively controlled switch for extending a calling line to said director, register switches in said director successively responsive to the subscriber's calling device for registering a called number, sending mechanism in said director controlled by said registers to transmit series of impulses, means for disconnecting the calling line from said director when the last series of impulses has been transmitted, and means for automatically disconnecting the calling line from said director before the last series of impulses is transmitted in case a register is not operated within a predetermined time after the preceding register is operated.

20 3. In a telephone system, a director, automatic switches having access to said director, means for operating one of said switches to extend a calling line to said director, registering mechanism in said director responsive to the subscriber's calling device to register a called number, sending mechanism in said director controlled by said registering mechanism for transmitting series of impulses, means for dissociating the calling line and director and for restoring the registering mechanism after the last series of impulses has been transmitted, and means in said director for rendering the director busy to the said automatic switches until the said registering mechanism is fully restored.

40 4. In a telephone system, a trunk line, a director, means for connecting the trunk line with the director, an operating conductor included in the connection, a switching relay in the trunk, register switches in the director, means for grounding said conductor at the trunk end thereof to operate said register switches, and means for grounding said conductor at the director end thereof to operate said switching relay.

50 5. In a telephone system, a calling line, a director, registering mechanism in said director responsive to the calling device on said line, sending mechanism in the director controlled by said registering mechanism, automatic switches responsive to said sending mechanism to extend a connection in the direction of the called line, means for connecting the calling line to the partially completed connection, and other switches directly responsive to said calling device to complete the connection to the called line.

60 6. In a telephone system, a director including registers responsive to a calling subscriber's calling device for registering the digits in a called telephone number, impulse transmitting mechanism in the director controlled by said registers to transmit a variable number of series of impulses, a series of automatic switches responsive to said series of

impulses to complete the connection from the calling line to the called line, and means for automatically starting the transmission of each series of impulses independent of control from said switches.

7. In a telephone system, a director including registers responsive to a calling subscriber's calling device for registering the digits in a called telephone number, impulse transmitting mechanism in the director controlled by said registers to transmit series of impulses, a series of automatic switches responsive to said series of impulses to trunk the call in the direction of the called line, said switches having directive and automatic trunking movements, and means in said director for introducing a definite minimum time interval between each series of impulses and the next succeeding series in order to provide time for the automatic trunk hunting operations of said switches.

25 8. In a telephone system, a director including means for registering all the digits in a called number, means for translating the digits which have to do with the office selection into a suitable office code, and impulse transmitting mechanism operated in accordance with said code, a series of automatic switches responsive to the code impulses to trunk the call to the desired office, and means in the director locally controlled for automatically starting the transmission of each series of code impulses independent of control from said switches.

30 9. In a telephone exchange system, inter-office trunk lines divided into groups and sub-groups, automatic switches operable in accordance with predetermined codes to trunk calling lines to said inter-office trunk lines, the said codes being divided into groups corresponding to said main groups of trunk lines, directors divided into groups, switching mechanism for selecting groups of codes by trunking calling lines to selected groups of directors, and means in the directors of each group for selecting particular codes in the corresponding code group.

40 10. In a telephone system, a local trunk line, means for connecting a calling line to said trunk line, a director, switching equipment controlled in accordance with a portion of the called telephone number to perform a preliminary trunking operation to connect the calling line with said director, registering means in said director controlled in accordance with another portion of the called number, an interoffice trunk line, sending mechanism in said director for transmitting series of impulses in accordance with a code determined by the operation of the said switching equipment and registering means, and automatic switches responsive to said series of impulses to connect said local trunk line with said interoffice trunk line.

45 11. In a telephone system, a first exchange,

- a plurality of other exchanges, a series of automatic switches for trunking calls from the first exchange to the said other exchanges in accordance with code numbers, a second series of automatic switches controlled successively by a calling subscriber in accordance with a plurality of characters in a called number to select the code corresponding to the desired exchange, said second series of switches each having a subscriber controlled directive movement and an automatic trunk hunting movement, and sending mechanism controlled in accordance with the selected code for operating said first series of switches.
12. In a telephone system in which connections are established by means of automatic directively controlled switches, a plurality of directors divided into groups, each director comprising means for controlling all the directly controlled switches involved in a complete connection, and the directors in each group being adapted to handle a different class of connections, and an automatic directively controlled switch operated by a calling subscriber for selecting groups of directors in accordance with the different classes of connections he desires to establish.
13. In a telephone system, automatic switches for establishing a plurality of different classes of connections, a different director for controlling said switches to establish each class of connections, a director selector controlled by a calling subscriber to select directors in accordance with the different classes of connections it is desired to obtain, and means for releasing the director selector and the selected director after each connection is established while maintaining the connection through said automatic switches.
14. In a telephone system, a plurality of exchanges divided into groups, a plurality of directors in one exchange divided into groups corresponding to the groups of exchanges, registering, translating and sending equipment in the directors of each group, and automatic switching mechanism controlled by calling subscribers for selecting groups of directors in accordance with the initial letters in the names of desired exchanges.
15. In a telephone system, a first exchange, a plurality of other exchanges, a plurality of different directors in said first exchange, there being one director for each of said other exchanges, an automatic switch for trunking calls from said first exchange to said other exchanges, means in each director for controlling said switch to trunk calls to its associated exchange, and subscriber controlled means for selecting directors in accordance with the exchanges in which the called lines are located.
16. In a telephone system, means for connecting a calling and called line including a trunk line terminating in a first selector, said
- trunk line normally divided into two sections, directors arranged in groups, a director selector controlled by the calling subscriber over one section of said trunk to select an idle director in a particular one of said groups and to extend the two sections of said trunk thereto, registering means in the selected director, transmitting means in the selected director controlled by said registering means for sending impulses over the second section of said trunk to operate said first selector and a series of other switches to complete the connection, and means for connecting said sections and for releasing the director selector when the connection is completed.
17. In a telephone system, means including line switches and first selector switches for connecting calling and called lines, trunk lines extending between the line switches and first selectors, directors for controlling said first selectors divided into groups, and director selectors associated with the said trunks and directly controlled from calling lines to select groups of said directors.
18. In a telephone system, a director, a calling line, means including an automatic switch responsive to the calling of a digit on the calling device on said line for trunking said line to said director, and a series of automatic switches controlled by said director for connecting the said calling line with a called line over a path excluding said first switch.
19. In a telephone system, a director including registers responsive to a calling subscriber's calling device for registering all the digits in a called number except the first, an automatic switch controlled by said calling device in accordance with the first digit for trunking the calling line to said director, and a series of automatic switches controlled by said director for connecting the said calling line with a called line over a path excluding said first switch.
20. In a telephone system, a trunk line comprising two normally disconnected sections, an automatic switch in which the second section terminates, means for extending a calling line to the first section, a director, automatic switching mechanism controlled by the calling subscriber for connecting said director with said trunk line, a device in said director responsive to the connection of the director with the trunk line for transmitting a series of impulses to said switch over the second section of said trunk line, and means operated automatically at the end of said series of impulses for uniting said sections and disconnecting said receiver.
21. In a telephone system, a trunk line comprising two normally disconnected sections, an automatic switch in which the second section terminates, means for extending a calling line to the first section, a director,

- automatic switching mechanism controlled by the calling subscriber for connecting said director with said trunk line, a device in said director responsive to the connection 5 of the director with the trunk line for transmitting a plurality of series of impulses over the second section to operate said switch and other switches, and means controlled by the director responsive to the completion of the 10 impulse transmission for uniting said sections and disconnecting said director.
22. In a telephone system, a trunk line comprising two normally disconnected sections, an automatic switch in which the second section terminates, means for extending a calling line to the first section, a director, a plurality of automatic switches controlled by the calling subscriber for connecting said director with said trunk line, a device in 15 said director responsive to the connection of the director with the trunk line for transmitting a predetermined set of code impulses to said switch over the second section of said trunk line, and means for uniting said sections and for disconnecting said director at 20 the end of the series of impulses.
23. In a director for use by a calling subscriber in controlling automatic switches, a sending switch, means for operating said switch to transmit a plurality of predetermined series of impulses, means for automatically restoring said switch to normal after each series of impulses, and means responsive to the seizure of said director for 25 starting the transmission of the first series.
24. In a telephone system, a plurality of directors comprising means for transmitting series of impulses according to different predetermined codes, each director being set for 30 a different code, a switch directly controlled by a calling subscriber for selecting a desired one of said directors, a train of switches controlled by the selected director according to the code for which it is set, and 35 means for connecting the calling line with the first switch in said train over a path excluding the director selecting switch.
25. In a telephone system, a trunk line, a director comprising register switches and sending mechanism controlled thereby, means for connecting said director to said trunk line, an operating conductor extending between the trunk and director after the two are connected, means for associating said conductor 40 with said register switches successively, a relay in said director for opening said conductor and for placing a potential on the section thereof extending to the trunk, and means in the trunk responsive to said potential for disconnecting said director from the 45 trunk.
26. In a telephone system, a director comprising register switches and sending mechanism controlled thereby, automatic switches for extending calling lines to said director, 50 a release circuit for said register switches, a relay controlled over said circuit, and means controlled by said relay for making said director busy to said automatic switches.
27. In a telephone system, a director comprising register switches and sending mechanism controlled thereby, automatic switches for extending calling lines to said director, release magnets for said register switches, and a relay energized in series with said release magnets for rendering said director 55 busy to said automatic switches.
28. In a telephone system, a director comprising register switches and sending mechanism controlled thereby, automatic switches for extending calling lines to said director, a release relay in said director held energized while the same is in use, a counting switch constituting part of said sending mechanism, a second relay controlled jointly by said counting switch and said release relay, and means controlled by said second relay for making said director busy to said automatic switches.
29. In a telephone system, a director comprising register switches and sending mechanism controlled thereby, automatic switches for extending calling lines to said director, a release relay in said director held energized while the same is in use, a sequence switch for 60 causing said register switches to successively control said sending mechanism, a second relay controlled jointly by said sequence switch and said release relay, and means controlled by said second relay for making said director 65 busy to said automatic switches.
30. In a telephone system, a train of automatic switches for connecting a calling and called line, a director, register switches in said director, a sending device controlled by 70 said register switches for operating part of the switches in said train, and a calling device on the calling line for setting said register switches and for operating the rest of the switches in said train.
31. In a telephone system, a calling line, a calling device at the station on said line, a director, register switches in said director responsive to the said calling device, a second calling device in said director controlled 75 by said register switches, automatic switches responsive only to said second calling device, and other automatic switches accessible by way of said first mentioned automatic switches and responsive to the said first calling device.
32. In a telephone system, a calling line, a calling device at the station on said line, a director, register switches in said director responsive to the said calling device, a second calling device in said director controlled by 80 said register switches, automatic switches responsive only to said second calling device, and other automatic switches responsive to the said first calling device and accessible only 85.

through switches set by said second calling device.

33. In a telephone system, a calling line, a calling device at the station on said line, a director, register switches in said director responsive to the said calling device, a second calling device in said director controlled by said register switches, automatic switches responsive to said second calling device, and other automatic switches responsive either to said second or said first calling device depending on whether or not said first mentioned automatic switches have been set by the time the first calling device is operated to control the said other automatic switches.

34. In a telephone system, a trunk line in two sections, means for connecting a calling line to the first section, a director and means for connecting the same to the trunk line responsive to the call, register switches in said director controlled over the calling line and said first section, a sending device controlled by said register switches successively to transmit series of impulses over the second section, means for starting said device responsive to the setting of a predetermined number of registers, and means responsive to the transmission by said device of all the impulse series determined on for uniting said sections and for disconnecting said director, provided the transmission of such series of impulses is accomplished before the setting of the next register is begun.

35. In a director, a plurality of registers, means for setting said registers according to the digits in a called number, a sending device for transmitting series of impulses, a sequence switch, a plurality of operating circuits for said device under the sole control of said sequence switch and said register switches, and a plurality of stopping circuits for said device also under the sole control of said sequence switch and register switches.

36. In a director, a plurality of register switches, means for setting said registers according to the digits in a called number, a sending device for transmitting series of impulses, directive trunking switches responsive to said impulses, and starting and stopping circuits for said device controlled by said register switches independent of said trunking switches.

37. In a telephone system, a trunk line terminating in a first selector, a branch of said trunk line terminating in a director selector, both said selectors being of the numerical or directive type, other similar trunk lines terminating in first selectors and director selectors, groups of second selectors accessible to said first selectors, groups of directors accessible to said director selectors, and means in said directors for registering digits in called numbers and for controlling said first and second selectors in accordance therewith.

38. In a telephone system, a trunk line, a di-

rector selector associated with said trunk line, directors accessible to said director selector, second director selectors accessible to said director selector also, other directors accessible to said second director selectors, and means in all said directors for registering digits in called numbers and for controlling trains of switches to extend said trunk line to called lines.

39. In a telephone system, a trunk line, directors comprising means for registering a plurality of digits in called numbers, other directors comprising means for registering a greater plurality of digits in called numbers, means including a number of directly controlled switches for connecting said trunk line with one of said first mentioned directors, means including a smaller number of directive switches for connecting said trunk line with one of said other directors, and means in all of said directors for controlling trains of automatic switches to extend said trunk line to called lines.

40. In a telephone system, a trunk line, directors each including a one digit office register, other directors each including a two digit office register, two serially related directive switches for connecting said trunk line with one of said first mentioned directors, a single directive switch for connecting said trunk line with one of said other directors, and means in all directors for operating trains of automatic switches to extend said trunk line to called lines.

41. In a telephone system, a plurality of groups of directors for registering digits in called numbers and controlling automatic switches accordingly, means for varying the control for any given set of registered digits depending on the group to which the director in use belongs, a selector switch arranged to be directly controlled by calling subscribers and having groups of contacts each assigned to a different one of said groups of directors, another group of contacts unassigned to any separate group of directors, and multiple connections between the contacts of said unassigned group and one of the assigned groups.

42. In a telephone system, a plurality of offices, each having a three digit office designation, said offices being grouped according to the initial digits in their respective designations, a common group of directors for handling calls to all groups of offices in which the individual offices are distinguished from each other by the second and third digits, and separate groups of directors for handling calls to the remaining groups of offices.

43. In a telephone system, a plurality of directors all accessible to the same calling subscriber, a sending device in each director for transmitting series of impulses according to office codes, an office register in each director for selecting codes, and different control

means intervening between the office registers and the sending devices in the several directors so that the same setting of the office registers in any two directors will produce different codes.

44. In a telephone system, a plurality of directors all accessible to the same calling subscriber, a sending device in each director for transmitting series of impulses according to office codes, an office register in each director for selecting codes, means including an intermediate distributing frame in each director, whereby the office registers are given control over the sending devices to select codes as set forth, and different cross connections on said distributing frames so that the same setting of the office registers in any two directors will produce different codes.

45. In a telephone system, means for selecting office codes corresponding to different office designations in called numbers, said means comprising a directly controlled and automatic hunting switch operated in its directive movement in accordance with the first digit of an office designation, and a register switch selected by said first switch in its hunting movement and operated in accordance with the remaining digits of such office designation.

46. In a telephone system, a register control circuit, a switch control circuit, a plurality of groups of directors, registers in each director adapted to be set over said register control circuit, a sending device in each director for transmitting impulses over said switch control circuit, and a switch directly controlled by a calling subscriber to extend both said circuits to an idle director in any desired one of said groups.

47. In a telephone system, a trunk line comprising two sections, a first selector in which the second section terminates, a director, a director selector controlled over the first section in accordance with a digit in a called number for extending the two talking conductors of the second section to said director, a line relay in said first selector energized from the director over said talking conductors in series, registers in said director set according to other digits in a called number, and a sending device controlled by one of said registers for interrupting the circuit of said line relay.

48. In an automatic telephone system, calling and called lines, a first one of a plurality of linking switches each terminating a link for linking a connection from the calling line to the called line, a calling dial on the calling line for transmitting series of directive control impulses, a storing device, an auxiliary switch, means for directly operating the said auxiliary switch from the dial to select the storing device, and means responsive to the selection of the storing device for automatically operating the storing device to di-

rectively operate the said first switch into connection with a said link.

49. In an automatic telephone system, a calling and called lines, a first one of a plurality of linking switches each terminating a link for linking a connection from the calling line to the called line, a calling dial on the calling line for transmitting series of directive control impulses, a storing device, an auxiliary switch, means for directly operating the said auxiliary switch from the dial to select the storing device, and means responsive to the selection of the storing device for automatically operating the storing device to directly operate the said first switch into connection with a said link and incidentally disconnect the storing device from the connection and connect the calling line to the link leading to the said first switch, so that the dial on the calling line will be directly related to the switch terminating the link to which the said first switch is connected.

50. In an automatic telephone system, calling and called lines, a first one of a plurality of linking switches each terminating a link for linking a connection from the calling line to the called line, a calling dial on the calling line for transmitting series of directive control impulses, a storing device, an auxiliary switch, means for directly operating the said auxiliary switch from the dial to select the storing device, means responsive to the selection of the storing device for automatically operating the storing device to directly operate the said first switch into connection with a said link, and means whereby thereafter operating the said dial will be effective to directly directly operating the switch terminating the latter said link to progress the call towards the called line.

51. In an automatic telephone system, calling and called lines, a first one of a plurality of linking switches each terminating a link for linking a connection from the calling line to the called line, a calling dial on the calling line for transmitting series of directive control impulses corresponding to the prefix digit and the local digits of the called line, the prefix digit for progressing the call through the said first switch to a said link leading to a second one of said switches located in the office containing the called line, and the local digits for completing the call through the latter said switch to the called line, a storing device, an auxiliary switch, means for directly operating the auxiliary switch responsive to sending the prefix from the dial to select the storing device, and means responsive to selecting the storing device for automatically operating the said first switch to extend the call to said second switch, and means whereby then annexing the local digits from the dial will directly directly progress the call from the said second switch and

through other of said switches to the called line.

52. In an automatic telephone system, calling and called lines, a first one of a plurality of linking switches each terminating a link for linking a connection from the calling line to the called line, a calling dial on the calling line for transmitting series of directive control impulses corresponding to the prefix and the local digits of the called line, the prefix for progressing the call through the said first switch to a said link leading to a second one of said switches located in the office containing the called line, and the local digits for completing the call through the latter said switch to the called line, a storing device, an auxiliary switch, means for directly operating the auxiliary switch responsive to sending the prefix from the dial to select the storing device, means responsive to selecting the storing device for automatically operating the said first switch to extend the call to said second switch, and means whereby then annexing the local digits from the dial will directly directly progress the call from the said second switch to the called line.

53. In an automatic telephone system, calling and called lines, a first one of a plurality of linking switches each terminating a link for linking a connection from the calling line to the called line, a calling dial on the calling line for transmitting series of directive control impulses corresponding to the prefix and the local digits of the called line, the prefix for progressing the call through the said first switch to a said link leading to a second one of said switches located in the office containing the called line, the local digits for completing the call through the latter said switch to the called line, a storing device, an auxiliary switch, means for directly operating the auxiliary switch responsive to sending the prefix from the dial to select the storing device, means responsive to selecting the storing device for automatically operating the said first switch to extend the call to said second switch, and means whereby then annexing the local digits from the dial will directly progress the call from the said second switch to the called line, the storing device and the auxiliary switch being independently subject to use in a new call upon the said first switch being operated and before the call has been completed responsive to the annexing of the local digits from the dial.

54. In an automatic telephone system, calling and called lines, a first one of a plurality of linking switches each terminating a link for linking a connection from the calling line to the called line, a calling dial on the calling line for transmitting series of directive control impulses corresponding to the prefix and the local digits of the called line, the prefix for causing the progress of the call through the said first switch and another

said switch to a third switch in the office containing the called line, the local digits for causing the progress of the call through the said third switch and a plurality of succeeding switches to the called line, a storing device, an auxiliary switch, means for directly operating the auxiliary switch responsive to the sending of the prefix from the dial to select the storing device, and means responsive to the selecting of the storing device which will cause the storing device to directly progress the call to the said third switch, and means responsive to the annexing of the local digits from the dial which will set-up a condition in the storing device to cause the call to be further progressed to the called line.

55. In an automatic telephone system, calling and called lines, a first one of a plurality of linking switches each terminating a link for linking a connection from the calling line to the called line, a calling dial on the calling line for transmitting series of directive control impulses corresponding to the prefix and the local digits of the called line, the prefix for causing the progress of the call through the said first switch and another said switch to a third switch in the office containing the called line, the local digits for causing the progress of the call through the said third switch and a plurality of succeeding switches to the called line, a storing device, an auxiliary switch, means for directly operating the auxiliary switch responsive to the sending of the prefix from the dial to select the storing device, means responsive to the selecting of the storing device which will cause the storing device to automatically directly progress the call to the said third switch, and means responsive to the annexing of the local digits from the dial which will set-up a condition in the storing device to cause the call to be further progressed to the called line under automatic directive control of the storing device.

56. In an automatic telephone system, calling and called lines, a first one of a plurality of linking switches each terminating a link for linking a connection from the calling line to the called line, a calling dial on the calling line for transmitting series of directive control impulses corresponding to the prefix and the local digits of the called line, the prefix for causing the progress of the call through the said first switch and another said switch to a third switch in the office containing the called line, the local digits for causing the progress of the call through the said third switch and a plurality of succeeding switches to the called line, a storing device, an auxiliary switch, means for directly operating the auxiliary switch responsive to the sending of the prefix from the dial to select the storing device, means responsive to the selecting of the storing device which will cause the storing device to directly progress the call to the said third switch, and means responsive to the annexing of the local digits from the dial which will set-up a condition in the storing device to cause the call to be further progressed to the called line.

- vice which will cause the storing device to automatically directively progress the call to the said third switch, and means responsive to the annexing of the local digits from the dial which will cause the call to be further progressed to the called line. 5
57. In an automatic telephone system, calling and called lines, a first one of a plurality of linking switches each terminating a link 10 for linking a connection from the calling line to the called line, a calling dial on the calling line for transmitting series of directive control impulses corresponding to the prefix and the local digits of the called line, the 15 prefix for causing the progress of the call through the said first switch, the local digits for causing the progress of the call through the remainder of the said switches to the called line, a storing device, an auxiliary 20 switch, means for directively operating the auxiliary switch responsive to the sending of the prefix digit from the dial to select the storing device, means responsive to selecting the storing device which will cause the storing device to automatically directively progress the call through the said first switch in the direction of the called line, and means 25 whereby annexing the local digits from the dial will cause the call to be further progressed to the called line. 30
58. In an automatic telephone system, telephone lines, step-by-step switches including selectors and connectors, a register sender, a translating switch included in said register sender, means for automatically associating a calling line with said register sender, an impulse sender associated with said line to set said translating switch, means for causing said register sender to transmit sets of impulses to said switches in accordance with the setting of said translating switch, and a timing switch for delaying the transmission of each succeeding set of impulses to permit the corresponding selector to complete its trunk-hunting operation. 40
59. In an automatic telephone system, telephone lines, a plurality of offices wherein said lines terminate, automatic step-by-step switches, register senders at each office, means for automatically associating a calling line with an idle register sender, an impulse sender associated with said calling line for setting said register sender according to a given number of sets of impulses, means for causing said register sender to transmit a different number of sets of impulses to switches in the proper offices in tandem to route the call to the office wherein the called line terminates and to transmit additional sets of impulses to the switches at said office to properly set the same to select the desired line, trunks arranged in rows in said selectors, means for causing said selectors when positioned in a primary direction to auto- 50 matically hunt for an idle trunk in the row, 65 and a timing switch for delaying the transmission of the succeeding set of impulses until such trunk has been seized. 70
60. In an automatic telephone system, a series of automatic switches, a trunk line extending to the first of said switches and comprising two normally disconnected sections, means for extending a calling line to the first of said sections, a call director, means including a secondary line switch for automatically connecting said director to said trunk line at the junction of said sections responsive to the call, means in said director for registering the digits in the called number, and means in said director controlled by 80 said registering means for transmitting impulses over the two sides of the second section of said trunk line in series to operate said switches. 75
61. In an automatic telephone system, a series of automatic switches, a trunk line extending to the first of said switches and comprising two normally disconnected sections, means for extending a calling line to the first of said sections, a call director, means including a secondary line switch for automatically connecting said director to said trunk line at the junction of said sections responsive to the call, means in said director for registering the digits in the called number, 85 means for translating certain of said digits into a set of code digits, and a sending device in said director for transmitting series of impulses over the second section of said trunk line in accordance with the code digits and 90 the untranslated digits to operate said switches. 95
62. In a telephone system, a digit register, a plurality of other digit registers divided into groups, means for operating the first 100 named digit register to register a desired digit by selecting a group of said other digit registers, and means for then causing said first named register to automatically select an idle register in the selected group. 105
63. In a telephone system, a plurality of groups of registers, each group corresponding to a different digit, means responsive to impulses representing a digit in a telephone number for selecting the group of registers 110 corresponding to such digit, means for selecting an idle register in the group, means responsive to impulses representing another part of the same telephone number for operating the selected register, and an impulse sender controlled in accordance with the set position of any selected register. 115
64. In a telephone system, a train of switches for extending a calling line, means for connecting the calling line with the first 120 of said switches, means including an automatic directively-controlling hunting switch for extending a branch of said connection 125

from a point ahead of said first switch, and an automatic sender for transmitting series of impulses back over said branch connection to operate said train of switches.

65. In a telephone system, a sending device, a plurality of automatic switches directly controlled by a calling subscriber to associate his line with said sending device, and a second plurality of switches directly controlled by said sending device to extend the calling line to a called line over a path excluding said first plurality of switches.

66. In a telephone system, a plurality of groups of office registers, means for associating a calling line with an office register, said means including automatic switching mechanism controlled over the calling line to select one of said groups and an idle office register in the selected group, a sender controlled by the selected office register, and automatic switches directly controlled by said sender to extend the calling line over a path excluding said selector.

67. In a telephone system wherein a connection may be extended from a line by automatic switching apparatus, a plurality of groups of registering devices, each group bearing a different designation, means responsive to the transmission of the designation of any one of said groups over said line for extending an auxiliary branch connection from said line to an idle register in the group corresponding to the designation sent, said means including testing apparatus, means for setting the selected register over said line, and means for automatically operating said switching apparatus to extend the main connection from said line in accordance with the setting of the selected register.

68. In a telephone system, a line, automatic switches for setting up telephone connections from said line, said automatic switches being directly controllable by trains of impulses, a plurality of groups of registers, each group bearing a different designation, an automatic trunking switch having access to all of said groups of registers, means for operating said switch over said line to extend an auxiliary connection to an idle register in a desired group, and sending apparatus operated in accordance with the setting of the selected register to send trains of impulses to operate said automatic switches to set up a telephone connection from the said line.

69. In a telephone system, a line, a plurality of groups of registering devices, means responsive to directive control over said line for selecting a group of said devices and for selecting any idle device in the selected group, means responsive to further directive control for setting the selected device, automatic switching apparatus, and means independent of further directive control over said line for operating said apparatus to extend a connection

from said line over any one of a plurality of paths, the path used being dependent upon the device selected and the setting thereof.

70. In a telephone system, an office register having two directive movements, a calling line, an automatic switch having two selecting movements for trunking said line to said register, a series of automatic switches for extending a talking connection from said calling line, and a sending device controlled by said office register for operating said switches.

71. In a telephone system, a first exchange, a plurality of other exchanges, a series of automatic switches for trunking calls from the first exchange to the said other exchanges in accordance with code numbers, a second series of automatic switches controlled successively by a calling subscriber in accordance with a plurality of characters in a called number to select the code corresponding to the desired exchange, one switch in said second series having a hunting movement in addition to its directive movement, and sending mechanism controlled in accordance with the selected code for operating said first series of switches.

72. In a telephone system employing digit registers, a trunk line terminating at one end in the banks of a first automatic switch and at the other end in a second automatic switch, a relay group including a line relay interposed in said trunk line, a third automatic switch associated with said relay group, means for operating said third switch to select an idle register, contacts on said line relay for transmitting series of impulses directly to the operating magnets of the seized register, and a steering switch in said seized register for distributing the series of impulses to said magnets successively.

73. The combination, in a call director, of a two-digit register switch having bank contacts, and a sender having bank contacts, of a distributing frame interposed between the bank contacts of the register and the bank contacts of said sender, permanent connections between certain terminals of said distributing frame and the bank contacts of said register such that the same connection is effected with the distributing frame when the register is set into any one of a plurality of positions, permanent connections between said distributing frame and the bank contacts of said sender, and temporary connections between the contacts representing the register bank and the contacts on the distributing frame representing the sender banks.

74. In a telephone system, a trunk, means for extending a calling line to said trunk, a call director, means for automatically connecting said director to said trunk responsive to said extension of the calling line, means in

- 5 said director for registering the digits in the desired number as they are called, means for translating certain of said digits into a set of code digits, sending means in said director 5 for retransmitting series of impulses over said trunk in accordance with the code digits and the untranslated digits to extend the connection to the called line, means for starting said sending means upon the registration of the last digit to be translated, and means for disconnecting the director and for restoring it to common use responsive to said sending means catching up with said registering means.
- 15 75. In a telephone system, a trunk, means for extending a calling line to said trunk, a call director, means for automatically connecting said director to said trunk responsive to said extension of the calling line, means 20 in said director for registering the digits in the desired number as they are called, means for translating certain of said digits into a set of code digits, sending means in said director for retransmitting series of impulses 25 over said trunk in accordance with the code digits and the untranslated digits to extend the connection to the called line, means for starting said sending means upon the registration of the last digit to be translated, means for disconnecting the director and for restoring it to common use responsive to said sending means catching up with said registering means, and means also responsive to said sending means catching up with said 30 registering means for placing the further extension of the connection under the control of the calling subscriber.
- 35 76. In a telephone system, a trunk, a call director, means responsive to a call over said trunk for connecting said director therewith, a plurality of registers in said director, means for operating said registers in succession for registering the digits in a called number, sending means controllable by any one of said registers, means for placing the sending means under the control of said registers in succession, and means for disconnecting said director from said trunk responsive to the placing of the sending means under the control of an unoperated register.
- 45 77. In a telephone system, a register sender including means for registering a plurality of digits and for retransmitting series of impulses corresponding thereto, means for taking said register sender for use, means for starting the transmission of impulses before all the digits have been registered, and means responsive to the transmission of the last registered digit for freeing said register sender.
- 50 78. In a director, a two digit office register, a plurality of single motion digit registers, an input circuit normally extending to said office register, a device for transferring said circuit to the other registers, a sender controlled by said registers, and an output circuit over which said sender transmits impulses.
- 55 79. In a director for registering and retransmitting numbers, a translating switch, means for operating said switch responsive to the first digit received at said director, registers operated responsive to additional digits as they are received, and a sender 75 controlled first by said translating switch and then by said registers.
- 60 80. In a director, registers, a sending device for transmitting digits determined by the setting of said registers, a sequence 80 switch having a position for each digit to be transmitted, said switch normally standing in the position for the first digit, and means for advancing said switch after each digit is transmitted.
- 65 81. In a director, a plurality of registers, a setting circuit, a control switch for associating said registers with said circuit successively, a sending device controlled by said registers, and a starting circuit for said sending device completed by said control switch 85 in a particular position.
- 68 82. In a register sender, an input circuit, a steering switch, means for advancing said steering switch step by step to associate said 90 circuit with the registers in turn, an impulse sender controlled by the registers, and an operating circuit for said sender closed by said switch after a predetermined number of steps.
- 70 83. In a director, registering devices, a sending device, a sequence switch for placing said sending device under the control of said registering devices successively, a restoring wiper in said sequence switch having a bank 95 of contacts normally connected together, and means for conductively separating certain of said contacts while the director is in use.
- 75 84. In a director, registering devices, a sending device, a sequence switch for placing 100 said sending device under the control of said registering devices successively, a restoring wiper in said sequence switch having a bank 105 of contacts, certain of said contacts being electrically separated while the director is in use, and means for connecting said contacts together when the director is released.
- 80 In witness whereof, I hereunto subscribe my name this 25th day of March, A. D. 1922.
- 85 RODNEY G. RICHARDSON.
In witness whereof, I hereunto subscribe my name this 25th day of March, A. D. 1922.
- 90 MARTIN L. NELSON.
